UNITED STATES PATENT OFFICE.

WILLIAM W. LASKER, OF BROOKLYN, NEW YORK, ASSIGNOR, BY MESNE ASSIGNMENTS, TO POWERS ACCOUNTING MACHINE COMPANY, OF NEW YORK, N. Y., A CORPORATION OF DELAWARE.

AUTOMATIC TABULATOR ACCOUNTING MACHINE.

Application filed May 1, 1918. Serial No. 231,825.

To all whom it may concern:

Be it known that I, WILLIAM W. LASKER, a citizen of the United States, residing in Brooklyn, in the county of Kings and State of New York, have invented certain new and useful Improvements in Automatic Tabulator Accounting Machines, of which the following is a specification.

This invention relates to printing tabulating accounting machines actuated by perforated cards fed from a magazine to a card analyzer and then deposited in a suitable receptacle.

An object of the invention is to improve the construction, economy, convenience, accuracy, reliability and speed of machines of this kind and generally to improve the construction of such machines throughout.

Another object of the invention is to provide a conveniently arranged easily operated magazine for cards before feeding them to the analyzer.

Another object of the invention is to provide a suitable arrangement for automatically stopping the operation of the machine when the magazine becomes empty.

Another object of the invention is to provide a yieldable feed means for the magazine adapted at times to be held inoperative while the machine continues to run for taking totals.

Another object of the invention is to provide a suitable receptacle having a floating floor for receiving the cards from the analyzer.

Another object of the invention is to provide a control means adapted to be automatically operated to arrest the operation of the machines when said receptacle becomes full of cards.

Another object of the invention is to provide a curved apron or guide means for conducting the cards from the analyzer, in which they are vertically disposed, into the receptacle, in which they are horizontally disposed.

Another object of the invention is to provide an improved form of analyzer pin box provided with a novel form of analyzer bars and locking means for locking the bars after the analyzing pins have been projected through the perforations of the cards for

setting the control means for the accounting machine.

Another object of the invention is to provide flexible connections between the analyzer and the accounting machine for adapting any one of the various zones of perforations of the perforated card to cooperate with and control any unit of the adding and printing mechanism of the accounting machine.

Another object of the invention is to provide settable members for the analyzer adapted to be locked in set position for cooperation with the flexible connections back against the settable members for controlling the accounting machine.

Another object is to provide a designation change sensing means for sensing the termination of one group of cards of a kind and the commencement of a new group and automatically bringing about the taking of a total when such sensing takes place.

Another object of the invention is to provide yieldable means for reciprocating the pin box so that when cards are not fed to the analyzer such yieldable means will not be sufficient to overcome the spring controlled settable means cooperating with and opposed to the pins of the pin box, thereby preventing the undesired registration of the values in the accounting machine while no cards are being fed to the analyzer.

Another object of the invention is to provide means for locking the mechanism for feeding cards to the analyzer during the time a total is being taken.

Another object of the invention is to provide a total taking mechanism adapted to bring about the taking of a total in the accounting machine when a total taking card is fed to the analyzer.

Another object of the invention is to provide a new and improved stop motion or clutch mechanism adapted automatically to bring the machine to rest when the magazine becomes empty or the card receptacle becomes full.

Another object of the invention is to devise a printing tabulator actuated by perforated cards in which the printing elements and the tabulating elements are positively driven.

Another object of the present improvement is to construct a printing tabulator, the driving means of which comprises reciprocating rack bars that actuate the tabulating and printing elements.

Another object of the present improvement is to devise a printing tabulator actuated by perforated cards, embodying as one of its elements, a non-print mechanism which is for the purpose of preventing ciphers from being printed to the left of the type set up by the analyzer perforated cards passed through the machine.

Another object of the present improvement is to devise a tabulator having as one of its elements a mechanism for rendering any one of the type segments and its associated tabulator element inoperative both for printing and tabulating.

Another object of the present improvement is to devise a printing tabulator composed of a plurality of separate units or zones and having a mechanism through the medium of which any one of the zones may be divided, so that each zone may operate as a plurality of zones, each divided zone accumulating and printing data separate and independent from the rest.

Another object of the present improvement is to devise a printing tabulator having a reciprocating accumulating carriage and a yielding means for reciprocating this carriage by two different actions, one action controlling the carriage for accumulating and the other action controlling the carriage for taking a total.

Another object of the present improvement is to construct a printing tabulator, embodying a novel form of shift mechanism whereby the accumulating and printing elements of the machine are shifted from accumulating position to total taking position and vice versa.

Another object of the present improvement is to construct a printing tabulator having means arranged for locking out any one of the accumulating units so that the type segments associated therewith may set type for printing data, but will prevent the said data from being accumulated by the accumulating mechanism.

Another object of the present improvement is to devise a printing tabulator having a novel form of printing segments.

Another object of the present improvement is to construct a printing tabulator having an improved form of locking and alining mechanism for the type segments.

Another object of the present improvement is to construct a printing tabulator having a novel form of carrying mechanism adapted to kick back the rack bars, a novel form of cam for effecting the carrying and a novel means for actuating the cam.

Another object of the present improve-

ment is to combine a printing tabulator, a novel form of stop pin and naught stop construction whereby the naught stops are controlled by actuation of the stop pins.

Another object of the present improvement is to construct a printing tabulator having type segments, accumulating elements associated with the type segments, rack bars for driving the type segments, driving means for the rack bars, means for locking and releasing the driving means to and from the rack bars, and stops for positioning the rack bars and bringing about such release.

Another object of the invention is to provide means for holding the stops in position to control the rack bars, and means for releasing the holding means and restoring the stops.

Another object of the invention is to provide means for preventing retrograde movement of the rack bars and type segments before the locking and alining means has time to take hold.

Another object of the invention is to provide means for preventing the accidental moving back of more than one rack bar when certain of the rack bars are kicked back by the carrying mechanism.

Another object of the invention is to provide means for restoring the rack bars after they have been kicked back by the carrying mechanism.

Another object of the invention is to provide means for automatically depressing the abutment members adapting the rack bars for driving when a total is taken.

Another object of the invention is to provide an economical and efficient means for effecting the printing by the reciprocation of the paper carriage when the printing type have been set.

Another object is to provide convenient means for rendering the carriage reciprocating mechanism inoperative at will and for automatically rendering the reciprocating mechanism operative when totals are printed.

Another object is to provide convenient means for at will displacing the printing carriage laterally relative to the type so that substantially any part of the paper may be brought to the type.

Another object is to provide an efficient and convenient total signal means for indicating the fact that a figure is a total, this means operating by shifting the carriage to one side as the total is being printed, whereby the total is offset from the listed column.

Another object is to provide a new and improved method of mounting the paper supporting rolls.

Another object is to provide an economical and efficient platen for pressing the paper against the type.

Another object is to provide an improved method of feeding, supporting, clamping and releasing the paper and of adjusting the amount of feed of the paper.

5 Another object is to provide efficient means for preventing overthrow of the feeding when the machine is running at high speed.

Another object is to provide an improved 10 means for supporting, feeding and reversing the inking ribbon, and an improved means for inking the ribbon.

Still further objects and advantages of the 15 present improvement will be set forth in the following description and drawings in which,—

Fig. 1 is a side elevation of the complete machine.

Fig. 2 is a longitudinal sectional view 20 taken through the base of the machine showing the magazine, the analyzer and the card receptacle therefor.

Fig. 3 is a top plan view of the analyzing base.

25 Fig. 4 is a rear elevation of the machine.

Fig. 5 is a perspective view of the card magazine.

Fig. 6 is a fragmental sectional view 30 showing the picker block of the magazine and parts of the means for automatically stopping the machine when the magazine is empty.

Fig. 7 is an elevation of parts of said automatic means.

35 Fig. 8 is a plan view of the picker block showing said stop mechanism.

Fig. 9 is a longitudinal vertical sectional view of the analyzer.

Fig. 9^a is a face view of a latch plate.

40 Fig. 10 is a side elevation showing the supporting parts of the analyzer pin box and settable means.

Fig. 11 is a plan view of the connection support supporting the flexible connections 45 between the analyzer and the accounting machine.

Fig. 12 is a longitudinal vertical sectional view of the connection support showing the connections in elevation.

50 Fig. 13 is taken on the line 13—13 of Fig. 11.

Fig. 14 is a perspective view showing a detail of the method of supporting the flexible connections on the connection support.

55 Fig. 15 is a side elevation partly in section showing the designation change sensing means.

Fig. 16 is a similar view showing the reverse side of the sensing means.

60 Fig. 17 is an edge elevation of the sensing means taken from the left of Fig. 16.

Fig. 18 is a fragmental side elevation showing the parts in a different position.

Fig. 19 is a plan of the sensing means 65 parts being removed.

Fig. 20 is a longitudinal vertical sectional view showing parts of the drive levers for the analyzer feeding mechanism and pin box and means for locking the feeding mechanism.

70 Fig. 21 is a sectional view of the clutch mechanism or stop motion for the accounting machine and analyzer.

Fig. 22 is an elevation of one side of the units of the accounting machine.

Fig. 23 is an elevation of the other side of the unit.

Fig. 24 is a longitudinal sectional view of the accounting machine.

Fig. 25 is a vertical sectional view of the 80 terminal box for the terminals of the flexible connections leading from the analyzer.

Fig. 26 is a plan of this terminal box.

Fig. 27 is a side elevation of the terminal box.

Fig. 28 is a plan showing the various cams and their cooperating links and levers for operating the various mechanisms of the accounting machine.

Fig. 29 is a side elevation of the carry-over cam and its cooperating link.

Fig. 30 is a side elevation of the rack bar drive cam.

Fig. 31 is a side elevation of the terminal pin restoring cam.

Fig. 32 is a side elevation showing the accumulating and total taking cam.

Fig. 33 is a side elevation showing the sector alining and holding cam.

Fig. 34 is a plan of the numeral and zero 100 stop mechanism for stopping the rack bars.

Fig. 35 is a side elevation of this mechanism.

Fig. 36 is an end view of this mechanism.

Fig. 37 is a face view of a shutter supporting plate for supporting the shutters for holding the stops in set position.

Fig. 38 is a perspective view of one of the stop holding shutters.

Fig. 39 is a perspective view of one of the numeral stops.

Fig. 40 is a perspective view of the actuating levers and their controlling cam for actuating the accumulator carriage for accumulating or taking totals.

Fig. 41 is a vertical sectional view showing said levers and cams in accumulatin position.

Fig. 42 is a similar sectional view showing said levers and cams in position for taking totals.

Fig. 43 is a side elevation showing the total shift lever for shifting the total shift cam.

Fig. 44 is a horizontal sectional view taken on the line 44—44 of Fig. 43.

Fig. 45 is a rear end elevation partly in section of the accumulator carriage.

Fig. 46 is a plan of the same.

- Fig. 47 is a longitudinal vertical sectional view of the accumulator carriage.
- Fig. 48 is a side elevation of one of the type sectors detached.
- Fig. 49 is a fragmental side elevation showing the numeral type attached to the type sector.
- Fig. 50 is a sectional view on the line 50—50 of Fig. 49.
- 10 Fig. 51 shows a cipher cutout mechanism and is a fragmental side elevation of a registering and printing element showing the type segment and the zero support of the next lower order, both retracted from printing position.
- 15 Fig. 52 is a fragmental side elevation showing a portion of a type segment with its zero support moved to printing position by the cam of the next higher order.
- 20 Fig. 53 is a fragmental side elevation showing a type segment in retracted position and its roller adjusted to inoperative position.
- 25 Fig. 54 is a similar view showing a type segment in zero position, the zero support in nonprint position and the roller bracket in inoperative position.
- 30 Fig. 55 is a fragmental perspective view showing the zero supports and the adjacent cooperating parts.
- Fig. 56 is a side elevation of a cam roller bracket.
- Fig. 57 is a large view of the same.
- 35 Fig. 58 is a side elevation of a zero support.
- Fig. 59 is an edge view of the latter.
- Fig. 60 is a sectional view taken on the line 60—60 of Fig. 58.
- 40 Fig. 61 is a plan showing the registering and printing elements in the position of Fig. 52.
- Fig. 62 is a plan showing one element in the position of Fig. 54 and the remaining elements in the position of Fig. 61.
- 45 Fig. 63 is a face view of a decimal plate for printing decimals or separating means between characters.
- Fig. 64 is a face view of a strip of paper showing matter printed illustrating the operation of the cipher cutout mechanism.
- 50 Fig. 65 is an end elevation of the printing carriage showing one position of the parts.
- Fig. 66 is a similar view, parts being broken away, showing a different position 55 of the parts.
- Fig. 67 is a front elevation of the carriage.
- Fig. 68 is a sectional view of the detail taken on the lines 68—68 of Fig. 67.
- Fig. 69 is a plan of the carriage.
- 60 Fig. 70 is a rear-elevation of the same.
- Fig. 71 is a fragmental end elevation showing parts of the paper feeding mechanism and the release of the same.
- Figs. 72 and 73 show sections taken re-
- spectively on lines 72—72 and 73—73 of Fig. 69.
- Fig. 74 is a face view of the non-print locking plate.
- The herein described apparatus comprises an analyzer to which cards are fed from the card magazine, in which analyzer analyzing pins are brought to bear upon the perforated cards and such analyzing pins as find perforations in the cards passed therethrough and set settable members which cooperate with flexible connections which are moved thereagainst to set control stops in the accounting machine, which control stops position the reciprocating rack bars of the accounting machine to effect a positioning of type sectors and the operation of cooperating accumulators accumulating therein data set up upon the type sectors corresponding to the perforations in the cards that are analyzed in the analyzer. When the type sectors are thus set up, the printing carriage forces paper carried thereon against the type whereby the items set up by the type sectors are printed upon the paper. The various mechanisms of the apparatus are carried in or on the table or supporting stand 5 composed of angle iron frame pieces 6 between which are placed panels 7.
- The analyzing base frame 10 (Figs. 1 and 2) comprises side pieces 11 between which the various mechanisms of the analyzer are carried and a top plate 12 on which is carried the card magazine 13 in which are carried the cards to be analyzed, from which cards items are to be transferred to the accounting machine for printing and adding.
- The card magazine.*
- The card magazine comprises a pair of lateral magazine guides 15 secured upon the top plate (Figs. 2 and 5) between which are disposed a pair of bottom guides 18 (Fig. 3) on which the cards rest in vertical position between said lateral guides. At the vertical end of the magazine there are provided a pair of guide posts 20 fixed upon the top plate, upon which posts vertically slides a picker block 21 (Fig. 2) provided with a picker plate 22 forming a picker shoulder at its rear edge, adapted to engage over the upper edge of the forward-most card in the magazine as the picker block reciprocates as will be explained. In the top plate 12 beneath the picker shoulder there is provided a card opening above which are placed a throat block 24 and an adjustable block 25 forming therebetween a micrometer slot which is adjusted to permit only a single card to pass therethrough. The position of the block 25 is adjusted by means of an adjusting screw 26, secured in a bearing block

28 carried on the top plate, the adjusting screw being controlled by a suitable milled head. In order to press the cards in the magazine yieldably and continuously toward the throat block and the picker block, there is provided a follower 30 disposed between the lateral guides and resting upon the bottom guides. Forwardly of the magazine there are provided a pair of spring barrels 31, (Fig. 3) on each of which is wound a steel tape 32 extending back to the lower rod 34 disposed behind the follower. By this arrangement the follower is yieldably pressed forwardly in the magazine and holds the foremost card in position to be engaged by the picker shoulder and to be carried thereby through the micrometer slot. In order that the follower may be held back for the convenient placing of cards into the magazine, there are provided at the rear of the lateral guides and the bottom guides, the hold back notches 38, and the rear notches 39 (Fig. 2) into which the follower rod and the follower may be placed to hold the follower in retracted position while the cards are inserted. After the cards are thus inserted the follower is released, permitting the spring barrels to draw the same forwardly.

30 *The magazine picker reciprocating mechanism.*

Somewhat forwardly of the magazine there are provided upon the top plate 12 a pair of standards 40 (Figs. 3 and 20) on which are fulcrumed the elbow levers 41 having a rearwardly projecting end, having a rear end slot 42 in which is slidable a slide block 44 carried upon the reduced end 45 of the picker block. Said elbow levers 41 are each provided with a downwardly projecting arm having a lower end slot 46 in which is received a slide block 48 pivotally mounted upon a rounded projection 49 carried upon the upper arm 50 (Fig. 20) of each bell-crank 52 fulcrumed at 53 to the inner part of each side piece 11. Each of said bell-cranks comprises a rearwardly disposed arm 55 provided at its rear end with a roller 56 engaging in the cam groove 57 of the cam 58 carried upon the cam shaft 59. Said cam shaft 59 is driven as will be explained, and when thus driven the rearwardly disposed arm 55 is reciprocated by the cam groove 57 thus bringing about the reciprocation of the upper arm 50, whereby the elbow levers 41 are reciprocated thus causing the picker block to be reciprocated up and down for feeding cards through the micrometer slot.

The upper arm 50 comprises an upper element 60 and a lower element 61 pivotally connected to each other at 62, the upper element being provided with a projection 64 engaging the slot 65 of the lower element,

whereby the relative movement of the element is limited. A spring 66 strained between the hooks 67 carried on the respective elements yieldably holds the elements at one limit of movement so that when the upper element 60 is held against reciprocation, as will be explained, the lower element and the rearwardly disposed arm 55 may continue to reciprocate.

Longitudinally disposed in the upper part of the base (Figs. 2, 4 and 10) are a pair of supporting guide rods 70 on which are supported a pair of spaced analyzer plates 71 and 72 directly beneath the micrometer slot of the magazine. Cards passing downwardly through the micrometer slot are seized by a pair of rollers 74 and 75 (Fig. 2) mounted upon resilient shafts 76 (Fig. 1) carrying at their outer ends gear wheels 77 driven by the small gears 78 and 78' from the gear wheel 79, in turn meshing with a gear wheel 80 meshing with a gear wheel 81 carried upon the cam shaft 59. The shafts 76 are made slightly resilient so that the cards may be grasped by the rollers 74 and 75 and passed between the plates 71 and 72.

The card analyzer.

The analyzing plates 72 are provided with vertical rows of registering perforations 85 and 86 (Fig. 9). The cards are held in place between the analyzer plates by means of a reciprocating card gate 87 (Fig. 9) reciprocated by a pair of links 88 connected at their forward ends to downwardly extending projections 89 (Figs. 2 and 20) formed on the supporting side plates 80 pivotally connected at their rear ends to the pivot bolts 91 carried upon the upper elements 60 of the bell-cranks.

The forward ends of the side supports 90 are pivotally connected to a pendant link 94 suspended from the accounting machine supporting base 95 (Fig. 1) of the accounting machine. After a card has been analyzed between the analyzer plates 71 and 72, as will be explained, the bell-cranks 52 and the links 88 are reciprocated, thus opening the card gate 87 and permitting the card to be driven downwardly by means of the co-operating edge engaging rollers 96 and 97, (Fig. 10) the former being driven by and mounted on the short shaft 98 supporting the gear 78. The card is then received by the card apron 100 (Fig. 2) where it is grasped between rollers 101 and 102. The rollers 101 are carried on shafts 104 rotatably supported in the side pieces 11 and carrying small gear wheels 105 (Fig. 1') engaging the gear wheel 79. The rollers 102 are carried on movable shafts 107 respectively supported on the brackets 108 pivoted as at 109 upon the side piece 11 and provided with hooked arms 110 between which are strained a

spring 111, serving to hold said rollers 102 pressed against the rollers 101 for properly grasping the cards. Instead of having the shafts 107 supported on movable brackets, 5 it is only necessary to make the shafts 104 and 107 slightly resilient so that they may tend sufficiently to hold the rollers tightly between the cards.

10 *The card receptacle.*

From the apron 101 the cards are projected upon the floating floor 115 (Fig. 2) provided at its opposite ends with tubular guide pieces 116 slideable upon the vertical guide rods 118 15 supported upon the bottom piece 119, and by the upper brackets 120 supported upon the brackets 121 carried by the base frame. At the rear and end edges of the floating floor there are placed stop plates 124 adapted 20 to stop the cards upon the floating floor as they are received from the apron, the cards being firmly positioned against said supporting plates by means of the positioning rollers 125 carried upon the roller shaft 127 25 passing out through the sides of the frame and rotated by means of a small gear 128 (Fig. 1) meshing with the gear 79.

The floating floor 125 is yieldably held against downward displacement by means 30 of the tapes 130 (Fig. 4) wound about the spring barrels 131 mounted upon the brackets 121. As the cards continue to issue from the apron 100 and are positioned by the positioning rollers 125, the floating floor 115 35 is gradually pressed downwardly until the maximum number is received.

40 *The analyzing pin box.*

Each card as it is placed between the analyzing plates 71 and 72 is analyzed by the bringing forward of the analyzing pins carried in the analyzing pin box. The analyzing pin box is supported upon the supporting guide rods 70 (Figs. 9 and 10) and comprises 45 a forward guide plate 140, an intermediate guide plate 141 and the rear guide plate 142, held spaced apart by means of the spacing rods 143. To the ends of the pin box there are secured side blocks 144 having rollers 50 145 slideably supporting the pin box on the rods 70. Each side block is also provided with a rounded projection 147 received in the upper end slot 148 of the upper arm 149 of the bell-crank levers 150 (Fig. 20) pivoted 55 at 152 to the side piece 11 of the base frame, said bell-crank levers comprise a lower arm 154, provided at its forward end with a roller 155 engaging in the analyzing cam groove 156 provided in the cam wheel 58, whereby the bell-crank lever is reciprocated for the reciprocation of the pin box. The upper arm of the bell-crank lever comprises an upper element 158 and a lower element 159 pivoted together as at 160, the upper element 60 being provided with a projection 162 en-

gaging in an elongated slot 163 provided in the upper element whereby said elements are adapted for limited relative movement. The upper element is held at this forward limit of movement by means of the spring 164 70 strained between the hooks 166 carried on the respective elements.

The guide plates 140, 141 and 142 are provided with vertical rows of openings 170, 171 and 172 disposed in alignment with the 75 perforations 85 and 86 of the analyzing plates. Openings 171 and 172 are elongated vertically and in them there are disposed vertical rows of horizontal analyzing bars 174, adapted for limited vertical movement 80 in the openings and each provided with a pair of downwardly opening notches 176 and 177 receiving said rear and intermediate plates respectively, and having forward cam edges 179 and 180, the upper edge of 85 each analyzing bar between said notches being cut away to form an intermediate reduced portion 181. In the openings 85 and 170 are disposed the analyzing pins 185 disposed in alignment with the analyzing bars 90 and terminating rearwardly in heads 186 engaging behind the forward plate 140 whereby any analyzing pins that may have gone forward are retracted when the pin box is retracted. When the pin box moves 95 forwardly, the analyzing pins 185 are brought into engagement with the card being analyzed and if any analyzing pin finds a perforation in the card it passes forwardly through the card, such analyzing pin 100 and its associated analyzing bar being impelled to move forwardly because the weight of the analyzing bar is sufficient to prevent said cam edges 179 and 180 from sliding up on the lower edges of the perforations 171 and 172. However, should the analyzing pin be obstructed by contact with the card, as where no perforation is present, the resistance of the card is sufficient to force back the analyzing pin and the associated analyzing bar relatively to the guide plates 141 and 142, thereby causing the cam edges 179 and 180 to cam over the lower edge 110 of the openings 171 and 172.

Since the forward impelling force of the 115 guide plates against said cam edges is very slight and is not sufficient to effect an appreciable change in the parts of the analyzing mechanism, it is necessary to provide means for locking the analyzing bars relatively to the pin box after they have moved forward behind an analyzing pin which has found a perforation in the card. This locking means comprises a vertically slideable locking plate 188 vertically slideable in 120 the pin box and provided with slots 189 adapted to receive the analyzing bars, said slots being adapted to permit vertical movement of said analyzing bars when the locking plate is raised and to hold in engage- 130

ment with said aligned openings 179 and 180, the notch 177 of any forwardly disposed bar when the locking plate is lowered. If, however, any analyzing bar has remained stationary while the plates 142 and 188 move forward relative thereto, the plates 142 and 188 move forwardly relative to such bar until they are disposed as far forward as the reduced portion 181 of the locking bar. In 10 this position there can be no locking of the analyzer bar when the pin box continues to move further forward, permitting the analyzing pins which have been obstructed by the card to remain unlocked so that there 15 will be no forcing of the pin against the card.

In order to bring about this locking movement, there is provided a lug 190 secured to the outer face of the rearwardly extending side plate 191 secured to the locking plate. This lug is provided with a rounded projection 192 which engages in cam slots 193, provided in slotted plates 194 secured by means of screws 195 to the frame 10. 20 These cam slots 193 are of such shape that when the rounded projection is at its rearward position of movement, it engages in the rear part of the cam slot thus holding the locking plate 188 upwardly out of locking 25 relation with the analyzing bars. When the pin box moves forwardly the rounded projection moves to the forward lower part of the cam slot 193 causing the locking plate to be lowered, thereby holding the analyzing 30 bar which has moved forwardly into locking engagement with the rear plate 142, but permitting the reduced portion 181 of any analyzing bar that has been held back by a card to remain free from any locking 35 engagement with the locking plate 88.

When the pin box is retracted, those 40 analyzer bars 174 which have been forced back because of the absence of perforations in the cards, are restored by means of the restoring plate 196 caused on the rods 197 supported in the brackets 198 carried by the frame 10. Small rods 199 (Fig. 10) supported between the upper part of restoring plate 196 and the analyzer plate 71 45 help guide the pin box in its movement.

The settable pins.

Forwardly of the analyzing plates 71 and 72 there are disposed a pair of guide plates 200 and 201 provided with perforations in alignment with the perforations of the analyzing plates, and in which are slidably mounted settable pins 203 in alignment with the analyzing pins. Each settable pin 50 is provided at its upper edge with a triangular projection forming vertical rear shoulders 205, and forwardly inclined cam faces 206.

Forwardly of the fixed guide plates are the cross supports 207 carried on the side

pieces 11 and carrying the extension pin guide plates 208 and 209 in which are slidably disposed extension pins 210 in alignment with the settable pins and provided with collars 211 between which and said 70 plate 209 there are compressed springs 212 for yieldably pressing the extension pins and with them the settable pins rearwardly.

The analyzer plates 71 and 72, the forward fixed plates 200 and 201 and the extension pin guide plates 208 and 209 are all mounted upon the fixed supporting guide rod 70 and are additionally supported and held spaced from each other and the analyzer plates 71 and 72 by means of the additional guide rods 80 215 (Fig. 10).

The settable pins 203 are pushed forward by the analyzer pins 185 and are held in such position by means of vertically slideable latch plates 216 (Figs. 9 and 9^a) slideable in the 85 slotted cross piece 217, fixed to the fixed guide plate 201 and yieldably held down by small springs 218. These latches are provided with lateral recesses 219 providing shouldered projections 220 adapted to be 90 engaged and raised by the forward cam faces 206 and to snap behind the vertical rear shoulders 205 when the settable pins 203 are forced forwardly. Forward of the extension pin guide plate 209 there are disposed between the extension pins a plurality of rocking levers 222 intermediately fulcrumed on a fulcrum rod 223. At the upper end of each of said rocking levers there is pivotally secured a sensing finger 224 adapted to engage 100 over the associated latch plate when the rocking lever is rocked to the position shown in Fig. 9. At the lower part of each rocking lever there is provided a releasing finger 226 adapted to engage under the associated latch plate when the lower part of the rocking lever is rocked to a position to the rear of that shown in Fig. 9. In this last position the releasing fingers serve to release the latch plate of any settable pin that has been moved 105 forwardly, and this releasing is brought about by means of a releasing rod 227 carried at opposite ends upon a pair of releasing arms 229 (Fig. 2) fulcrumed at 230 to the side pieces 11 and provided at their lower 110 end with a roller 231 engaging a cam groove 232 on the inner face of the cam wheels 58.

The rocking levers 222 are manually rocked from one position to the other by means of the outwardly spring pressed rods 120 233 provided with adjusting shoulders 234 by means of which they may be held to adjusted position.

The movable flexible connections.

125

Side supports 90 (Figs. 2, 11 and 12) are provided with upper notches 235 in which are received projecting lugs 236 provided upon the side plates 237 to which are secured rear and intermediate vertical bars 229 at 130

the upper and lower ends of which are mounted the upper and lower rear supporting bars 240 and 241 and the intermediate supporting bars 243 and 244. Front vertical bars 245 are secured to the inner face of the forward end of said side supports and support the upper and lower front supporting bars 246 and 247. All of said supporting bars are provided with vertically aligned lateral slots 250 in which are received the reduced ends 251 (Fig. 14) of the tube receiving bars 252 each provided with a plurality of lateral recesses 253. Associated with each pair of upper and lower supporting bars are the outer and inner guide plates 255 and 256 each provided with laterally bent portions 257 and 258 secured to said supporting bars by means of screws 259 received in the perforations 260. The laterally bent portions of the inner guide plates are each provided with an angular shoulder projection 262 adapted to engage and hold said reduced ends 251 in said lateral recesses 250. In the recesses 253 of said tube receiving bars are received the rear guide tubes 264, the intermediate guide tubes 265 and the forward guide tubes 266, said guide tubes being held against longitudinal movement by means of their enlarged heads, and against lateral movement by means of the adjacent tube receiving bar. Between the rear guide tubes and the intermediate guide tubes there are disposed a plurality of flexible push cables 268 each comprising an outer casing secured in said tubes respectively and an inner wire 269 (Fig. 14) passing through the guide tubes and received at the rear end in rear tubular terminal pins 270 slidably mounted in the rear guide plates 255 and 256 and registering with the extension pins 210. Intermediate terminal pins 272 slidable in the intermediate guide plates receive the forward ends of the inner wires 269. Registering with the intermediate terminal pins 272 are the forward terminal pins 273 receiving the rear ends of the inner wires of connecting push cables 275 carried in the forward guide tubes 266, the connecting push cables 275 connecting the forward terminal pins 273 with the accounting machine as will be explained.

Any of the pairs of guide plates 255 and 256 are easily detachable from the supporting bars so that intermediate guide tubes 256 and the associated intermediate terminal pins 272 may be detached from the intermediate supporting bars 243 and 244 and reattached at a different part of the intermediate supporting bar so as to register with the forward terminal pins 273 at any part of the forward supporting bars 246 and 247. In this way it is possible to connect any of the extension pins 210 with any desired connecting cables 275 and thus connect the part of

the analyzer which analyzes a given part of a 65 perforated card with any unit of the accounting machine.

When settable pins 203 have been forced forwardly during the analyzing of any card and have then been locked in their forward position by means of the latch plate 216 (Fig. 9), at this time the upper arms 50 (Fig. 20) of the bell-cranks 52 move rearwardly bringing with them the side supports 90 and all of the mechanism mounted therebetween that the rear terminal pins 270 are forced back upon the extension pins 210 which are held forwardly by the settable pins 203. This movement causes the rear terminal pins 270 to be forced inwardly relative to the rear guide tubes 264 and relatively to the outer casing of the adjustable push cables secured thereto, thus causing the intermediate terminal pins 272, the forward terminal pins 273 and the inner wire of the connecting cable 275 to be pushed forwardly so as to operate the stops of the accounting machine, as is explained in the description of the accounting machine.

The tubular terminal pins 270, 272 and 273 are provided with flattened portions 277 (Fig. 14) forming shoulders for limiting the movement of the terminal pins in the guide plates 255 and 256.

Designation change sensing mechanism. 95

Upon the middle of the pin guide-plates 208 and 209 there is mounted a sensing mechanism supporting plate 280 (Figs. 15 to 19), carrying the sensing mechanism for sensing 100 the designation change when groups of cards of the one designation are followed by another group of a different designation. After placing a pile of cards in the magazine, the machine is started to operate thereon. The machine will first operate on and add the items of the first group and on the completion of the first group, the sensing mechanism will sense the change of the designation groups, take and print the totals 110 of the accumulator items, clear the machine and immediately start, without attention upon the next group, continuing in this manner until all the groups have been separately totaled. The mechanism for accomplishing this will now be described.

A ratchet bar 281 is provided with slots 282, which receive the pins 284 that are carried upon the plate 280, whereby it is slidably supported for movement across the supporting plate and is held in retracted position by means of the spring 285 strained between the out-turned lip 286 of the ratchet bar and the housing 288 which is carried upon the top plate 12 and housing the change sensing 125 mechanism.

The upper edge of the ratchet bar 281 is provided with a pair of actuating teeth 290

and 291 and a detent tooth 292. The ratchet teeth 290 and 292 are engaged by the down-turned projection 294 of the driving pawl 295, pivotally mounted upon the upper end 5 of the sensing lever 296 mounted on the shaft 299 carried in the side pieces 11. On this shaft are also mounted the rod supporting arms 300 carrying the contact rod 301 adapted to be contacted by the sensing fingers 224, when they are in their rearmost position as shown in Fig. 16, and when any one of them is raised by means of a latch plate 216. Only those rock levers 222 which correspond to the designation or key-member zones of the perforated cards are set so 10 the sensing fingers are moved to their rear position. Whenever a sensing finger 224 is raised once, as when the first card of the first group is sensed, the sensing lever 296 is 15 rocked and moves the ratchet bar 281 the distance of one tooth, whereupon the detent tooth 292 is engaged, as shown in Fig. 18, by the projection 305 carried upon the inner end 20 of the check pawl or detent 306 pivotally mounted upon the supporting plate 280. The pawl 295 and the detent 306 are held in engagement with said tooth by means of a spring 308 strained between the up-turned 25 hooked arms 309 and 310 of said pawl and 30 detent.

When the sensing lever 296 is again rocked, it forces the lip 286 against the terminal pins 312 of the total taking cable 314 and the lock releasing cables 315, having their inner 35 wires connected to said terminal pins and their outer casings fixed in the terminal block 316 fixed upon the supporting plate 280. When these terminal pins are pushed by this second movement of the lip 286, the 40 inner wires of these cables are actuated, the inner wire of the cable 314 bringing about the taking of a total, as will be explained, the inner wires of the cables 315 bringing about the locking of the feed mechanism of 45 the card magazine and holding the side supports 90 against backward movement, as will be shortly explained.

After the cables 314 and 315 have been thus actuated, the spring 285 draws the 50 ratchet bar 281 back to the position of Fig. 18. When the first card of the next group appears in the analyzer, a different designation perforation will appear, and the sensing lever will be rocked and thus again causing the taking of a total. When the machine 55 is cleared of cards and it is wished to start up with a new group of a different designation, the pawl 295 and the detent 306 are both raised to permit the ratchet bar to move. 60 to the position of Fig. 15. This is accomplished by means of the resetting slide 321 provided with a projecting pin 326, engaging under the projecting ends 327 and 328 of the pawl 295 and detent 306, and guided

in the slot 329 of the supporting plate 286. *Magazine feed and flexible connection locking mechanism.*

Slidably mounted upon the upper part of 70 the inner face of each side piece 11 (Fig. 20), of the base frame is a horizontally disposed locking slide bar 330 provided with longitudinal slots 331 receiving pins 332 carried on said side pieces, whereby said bar is 75 slidably mounted for limited movement in a horizontal direction. At the rear end of the slide bar there is pivotally mounted at 333 a latch 334 provided with a lateral lug 335 adapted to engage behind the upper projection 336 carried upon the upper end of each of said analyzing bell-crank levers 150, when said upper end is in forward position. The elbow detent 338 pivotally mounted upon the locking slide bar is provided with 80 a shoulder 339 adapted to engage under said latch to hold said lug 335 out of engagement with said projecting end 336. A terminal block 340 mounted upon each side piece 11 and disposed over the lower part of the 85 elbow detent 338 has mounted therein the outer casing of one of said lock releasing cables 315 (Fig. 16).

A spring 341 strained between the hooks 342 of the latch 334 and the elbow detent 338, 95 holds the detent in engagement with the latch and tends to move the latch downwardly.

When the inner wire of said cables 315 are 100 operated, the elbow detent is released from the latch 334 and permits the projection 335 to engage behind the projection 336 of the bell-crank lever whereby the locking slide bar 330 is drawn rearwardly, thus causing the cam face 343 (Fig. 20), to engage the lateral projection 344 carried on the locking pawl 345 pivotally mounted at 346 to the side piece 11. When this engagement takes place 105 said locking pawl is lowered against the action of the spring 348 strained between the lower arm 349 of the pawl and the forward end of the locking slide bar, by which spring 110 said locking slide is normally yieldably held at the forward limit of its movement and said locking pawl is held in upper position. 115 When this lowering takes place, the locking shoulder 350 of the locking pawl engages behind the pivot bolt 91 of the bell-crank so that the upper element 60 of the bell-crank, and therefore the elbow lever 41 and the 120 picker block of the magazine, are held against reciprocatory movement while the lower arm 55 of the bell-crank continues to reciprocate against the yielding resistance of the spring 66. This causes the feeding of 125 cards from the magazine to be suspended and prevents the actuation of the inner wires of the connecting cables during the time that the total is being taken by the accounting

machine as is to be explained. At the end of this time, the peripheral cam projection 355 of the cam wheel 58 comes into engagement with a roller 356 carried at the lower 5 end of the releasing lever 357 fulcrumed on the rod 358 carried between the side pieces 11, and raises said releasing lever and with it the releasing bar 360 pivoted to the lower end of the releasing lever. The releasing bar 10 360 is provided with a slot 361 receiving a screw 362 carried upon the side piece 11, whereby said releasing bar is slidably under said latch 384. When the releasing lever 357 is thus raised, the releasing bar 360 causes 15 the latch 384 to be released from the end projection 336, thereby permitting the locking slide bar to move forward and permit the locking pawl 345 to be raised out of engagement with the pivot pawl 91, thus releasing 20 the upper element 60 of the bell-crank and permitting the feeding of cards to be resumed.

Total card sensing mechanism.

25 If for any reason it should be desired to keep the sensing mechanism above described out of operation and depend upon the well-known total taking cards for bringing about the operation of taking a total, this may be 30 done by means of the mechanism shown at the middle of Fig. 2 and the lower part of Fig. 9.

This mechanism comprises a total taking pin 365 slidable in perforations in the lower part of the plates 71, 140 and 142, and adapted 35 to be forwardly spring-pressed by means of a spring 366 strained between the plate 142 and the down-turned portion 367 of said pin. When a total is to be taken, a total taking card which may be provided 40 with a perforation or a cut-away portion of the edge thereof, is fed between the analyzer plates, and when the pin box moves forwardly, the total taking pin 365 passes through said perforation or cut-away 45 portion and actuates the total taking lever 368 fulcrumed upon the apron 100 and adapted to lower the plunger support 370 (Fig. 2) so that the plunger 371 slidably carried thereon will be in front of the terminal pin 372 of the total taking cable 373 having its outer casing fixed in the terminal block 374. When the support 370 is thus disposed from in front of the said terminal pin, it permits the plunger 371 to be moved 55 forwardly to engage said terminal pin to actuate the total taking mechanism of the accounting machine. The plunger 371 is actuated by means of a cam lever 375 fulcrumed on the boss 376 and provided with 60 an intermediate roller 377 adapted to be engaged by the cam 378 carried upon the cam shaft 59. The plunger 371 is yieldably held retracted by means of a spring 380 compressed between the support and the outer 65 head 381 of the plunger. The plunger is

held in the support by means of the inner head 384.

Automatic stop motion.

The improved stop motion and clutch 70 mechanism of the machine is located on a lower member 389 of the base frame 10 (Figs. 2 and 21), and comprises a worm-housing 390 in which is mounted the worm 391 fixed on the longitudinal drive shaft 392 rotatably 75 mounted in the lower part of said housing and connected by a belt 293 to an electric motor M (Fig. 4). In the upper part of the worm housing there is rotatably mounted a gear shaft 394 disposed transversely to 80 said drive-shaft and to the frame of the machine and mounted in suitable anti-friction bearings 395. On said gear shaft 394 is fixed a worm gear 397 meshing with said worm 391 and constraining said gear shaft 85 to rotate when the shaft 392 is driven. On the inner projecting end of the gear shaft 394 is fixed a collar 398 on which is secured by means of screws 399 a clutch member 400 provided with radial arms. Adjacent to 90 the worm housing there is provided a counter-shaft bracket 401 in which is rotatably mounted a counter-shaft 402 disposed in alignment with the gear-shaft 394. Upon the inner end of this counter-shaft is fixed a 95 clutch pin bracket 404 provided with a clutch pin bore 405 parallel to the counter-shaft 402 and spaced a considerable distance therefrom. In opposite ends of said bore there are fixed bushings 407 and 408 in 100 which are slidably received a clutch pin 409. On an intermediate part of the clutch pin is fixed an actuating collar 410 provided with a spiral groove 411 in which loosely engages a pin 412 fixed in the clutch pin bracket. Between said actuating collar 410 and the bushing 408 is disposed a compression spring 414 which yieldably holds the clutch pin disposed between the arms of the clutch member 400.

110 Since the pin 412 is fixed in the clutch pin bracket, rotary movement of the clutch pin brings about a corresponding endwise movement thereof for retracting the clutch pin from between the arms of the clutch member 400. On the other hand, when the clutch pin is released, the compression spring 414 causes the same to again engage between said arms.

115 In order to bring about this rotary movement, there is provided an arcuate rack lever 418 (Fig. 2) fulcrumed on an extension 419 of the clutch pin bracket 401. This rack lever is provided with teeth adapted to engage with the pinion 420, (Fig. 21), fixed 120 upon the outer end of the clutch pin 409. Beneath the rack lever there is provided in said member 389 a spring bore 421 in which is compressed a spring 422 which yieldably 125 presses a plunger block 424 against the rack 130

lever 418 and holds the rack lever in engagement with the pinion 420.

Also fulcrumed upon the extension 419 is the actuating lever 426 provided with a bifurcated portion 427 loosely receiving a pin 428 projecting from the rack lever 418. The lower arm of the actuating lever 426 is connected by means of a link 430 with the lower arm of a locking lever 431 intermediate 5 fulcrumed on the member 389 and provided with a locking shoulder 432 adapted to engage under the free end of the rack lever 418 and hold the rack lever in engagement with the pinion. It will be noted that there is sufficient play between the pin 428 and the bifurcated part 427 to bring about the release of the locking lever 431 before the rack lever is rocked downwardly by the anti-clockwise movement of the actuating lever 426.

When it is desired to cause the clutch mechanism to clutch, the actuating lever is actuated in anti-clockwise direction by the actuating rod 436, passing through the front panel 7, which first brings about the release of the locking lever 431 and then the downward movement of the rack lever 418 until the outer locking arm 437 thereof is caught on the shoulder 438 of the latch 440 pivotally 25 mounted on the extension 419 and pressed into engagement with said locking arm by the spring 441. This downward movement of the rocking lever releases the pinion 420, whereupon the clutch pin 409 moves into 30 clutching engagement with the clutch member 400 and the counter-shaft 402 is rotated. In order to cause the unclutching of the clutch mechanism, the latch 440 is released, thus permitting the rack lever 418 to move 35 into engagement with the pinion under the action of the spring 422. This causes the clutch pin to be rotated, and therefore withdrawn from engagement with the clutch member 400.

40 The counter-shaft 402 (Fig. 2) has fixed thereon the gear wheel 445 which meshes with the gear wheel 446 fixed on the cam shaft 59, whereby rotation is imparted to the cam shaft when the counter-shaft is rotated.

45 When enough cards are fed from the analyzer to cause the floating plate 115 to be moved nearly to its lowest limit, it is desirable that the machine be automatically stopped 50 until the operator can remove the cards and restart the machine. This automatic stopping is brought about by the pressure of said floating plate against the inner wire of the flexible push cable 448 (Fig. 2) having 55 the ends of its outer casing fixed in the terminal block 450 on the bottom plate 119 and the lower terminal block 451 fixed on the lower part of the extension 419. This causes 60 the release of the latch 440 and the unclutching of the clutch-mechanism.

It is also desirable that the clutch be unclutched and the machine be brought to rest should all of the cards be fed from the magazine, and the magazine thus become empty. The mechanism for accomplishing this is 70 shown in Figs. 5 to 8, and will now be described.

A vertically movable picker block 21 is provided with a plunger bore 460 disposed transversely of the picker block and longitudinally of the card magazine and in alignment with the plunger opening 461 in the follower 30. The bore 460 is formed with an inner shoulder 464 and in the bore there is slidably disposed a plunger 468 adapted to be 75 spring pressed inwardly toward the cards by means of a spring 469 disposed between said shoulder 464 and the head 470 of the plunger. The outer end of the plunger is provided with an elongated actuating block 472 80 adapted when the plunger is pressed to the position shown in Fig. 6 by means of cards in the magazine to be disposed out from under the engaging head 474 (Fig. 7) of the lever 475 fulcrumed on the sensing mechanism housing 288. Should there be no cards in the magazine, the plunger is pressed inwardly by means of the spring until its inner end passes through the plunger opening 461 and the block 472 passes under the 85 engaging head 474 of the lever 475. When this takes place the upward movement of the picker block causes the block to engage the engaging head 474 and rock the lever. This rocking causes the active end 476 of 90 the lever to engage the terminal pin 478 of the flexible push cable 479 having its outer casing fixed in the terminal block 480. The other end of the flexible push cable 479 has its outer casing fixed in the terminal block 105 451 (Fig. 2) and its inner wire adapted to engage the latch 440 for tripping the latch and releasing the rocked lever 418 for bringing about unclutching of the clutch mechanism as explained above. From this, it 110 will be seen that whenever the magazine becomes empty, the block 472 moves into operating relation with the flexible cable 479 and brings about the stopping of the machine.

115 Whenever the clutch mechanism is unclutched for arresting the machine, it is desirable that the motor M driving the drive shaft 392 be also brought to rest and this is accomplished by means of the flexible connection 485 (Fig. 1) having its inner end of its outer casing fixed in the terminal block 486 on extension 419 and the outer end of its casing fixed in the terminal block 487 120 mounted in the neighborhood of the release switch diagrammatically indicated at 488 which controls the electric current supplied to the motor. Therefore, whenever the rack lever 418 is raised for releasing the clutch, the inner wire of said cable 485 is actuated 125

by the actuating arm 491 of the rack lever which brings about the tripping of the latch 492 of the switch 488, thus permitting the contact blade 493 to move under the 5 action of the spring 494, out of engagement with the contacts 495 interposed in the circuit controlling the motor. This switch is shown only diagrammatically since it forms no part of the present invention.

10 *Operation of the analyzing and associated mechanisms.*

The follower 30 of the card magazine 13 is drawn back and cards placed therein with 15 their lower edges resting against the bottom guides 18 and the forward face of the pack of cards pressed against the picker block by means of the follower as it is yieldably drawn forward by the tapes 32 under the 20 action of the spring barrels 31. If the designation change sensing mechanism is to be used, the rock levers 222 associated with the zone of the perforated card representing the designations, is rocked outwardly by means 25 of the rod 233 so that the sensing fingers 224 of that zone are brought over the latch plates 216 associated with that zone. The other rock levers 221 are rocked inwardly so that the releasing fingers 226 engage under 30 the latch plates 216 of those zones in which adding is to take place.

The nob 333 is raised so as to be sure that the ratchet bar 281 is released. The push button 497 of the switch 488 is lowered thereby starting the motor, the rock lever 418 is by means of the rod 433 moved out of engagement with the pinion 420 and there held by means of the latch 440, whereupon, the cutout mechanism is clutched in and the 40 cam shaft 59 rotates and the bell-cranks 52 reciprocate bringing about the reciprocation of the picker block and the feeding of the cards. As the cards are fed downwardly, the links 88 at the same time move outwardly and close the card gate 87 (Fig. 9) and the card is fed between the analyzer plates 71 and 72 and is held there by the gate 87. After this has taken place the reciprocation of the bell-crank levers 150 50 causes the pin-box to move forwardly forcing all of the analyzing pins 185 toward the card at the time between the analyzing plates. Those analyzing pins which do not find perforations in the card are held stationary by the card while those pins which do find perforations move forwardly because of the resistance of the cam faces 179 and 180 against the guide plates 141 and 142. During this movement the locking 60 plate 188 moves forward with the pin-box and then locks those pins which have moved forward and leaves unlocked those which have been held back by the card. Those pins which have moved forward push the 65 settable pins 203 forward until the latch

plates 216 are raised and snap back behind the shoulders 205 thus locking the settable pins in position. Those latch plates which correspond to designating zones of the card raise the sensing fingers 224 which have been 70 set back, thus bringing about the operation of the sensing lever 296, and the movement of the ratchet bar 281 until the tooth 292 is actuated by the projection 305 of the detent 75 306.

When the detents are thus locked the bellcranks 52 rock back thus causing the card gate 87 to release the card which is then between the analyzer plates, whereupon, this card is passed outwardly over the apron 100 80 and is positioned by means of the positioning rollers 125 and the stop 124 upon the floating floor 115.

While the settable pins are still rocked forward and as the bellcranks rocked rearwardly as just stated, this movement of the bellcranks forces the side plates 90 and all of the mechanism contained therebetween to move backwardly against the extension pins 212 which have been forced forwardly 90 by the settable pins, whereupon, the inner wires of the cables 268 and 275 are forced forward relatively to their casings, whereupon, the inner wire of the cables 275 brings about the setting of the numeral 95 stops of the accounting machine as will be explained.

After this movement has taken place the bellcranks 52 and the associated mechanisms move forwardly and the releasing rod 227 100 (Fig. 2) is raised, whereupon, those raising fingers 226 which have been set backwardly under the latch plates 216 raise the associated rocked plates and release the settable pins 203 which do not correspond to 105 the designating zones of the card, whereupon, these settable pins and their associated extension pins 210 are forced back under the influence of the springs 212. The above operation of the pin box and the parts controlled thereby is repeated until all of the cards of the same designation are analyzed and the data thereof transferred to the accounting machine. When, however, a new group of cards of a different designation 110 falls just behind the previous group, different settable pins 203 relating to the designating zone are actuated thus raising the associated latch plates 216 and releasing the previously set settable pins. This raising of 115 the latch plate brings about another rocking of the sensing lever, whereupon the ratchet bar of the sensing mechanism is moved another space, but since there is only one detent tooth 306, the ratchet bar is 120 not locked in this new forward position and when the sensing lever rocks back to the position of Fig. 18, the ratchet bar moves back with it one space until the detent tooth 305 is engaged by the ratchet tooth 306. 125 130

This second movement of the ratchet bar 281 causes the lip 286 to engage the terminal pins 312, whereby movement is communicated through the cable 314 to the total taking mechanism of the accounting machine, thus bringing about the taking of a total.

At the same time the cables 315 communicate motion to the elbow detent 338 (Fig. 20) thus causing the lateral lug 335 to be dropped behind the end projection 336 whereupon the locking pawl 345 locks behind the pivot bolts 91 and holds the feeding mechanism from feeding any additional 15 card to the analyzer while the first card of the new group, which caused the operation of the sensing mechanism and the taking of a total, remains in the analyzer while the total is being given.

20 When the sensing lever was rocked the second time for bringing about the taking of this total, the ratchet bar of the sensing mechanism is not locked in the new position, but moves back under the action of its 25 spring to the position to which it was moved before the additional movement which brought about the taking of a total. Therefore, when a third group of cards is fed to the analyzer, the first card of the new group 30 will cause the sensing mechanism to be rocked once thus bringing about the taking of a total in the manner just explained.

If instead of depending upon the designation change sensing mechanism it is 35 preferred to use the ordinary total taking card, total taking cards are inserted in the pack of cards at the point where the total is to be taken. When such a card is fed to the machine the total taking finger 365 40 (Fig. 9) finds an opening in the edge of the card and moves through such opening under the action of the spring 366 and rocks the trip lever 368 and permits the plunger to move forward and actuate the total taking 45 cable which leads to the total shift mechanism of the machine and thus brings about the taking of a total, after which the gate 87 being opened permits the total taking card to pass out with the other cards into 50 the card receptacle. When a sufficient number of cards have been analyzed to cause the floating floor to engage the terminal pin of the inner wire of the cable, the clutching mechanism is unclutched thus causing the 55 machine to come to rest.

On the other hand, should the cards in the card magazine give out, the elongated head of the plunger (Fig. 7) rocks the lever 475 and the cable is actuated thus 60 releasing the clutch. In every case the releasing of the clutch brings about the actuation of the flexible connection for 485 (Fig. 1) and causes the trip lever 492 to release the contact blade 493 and bring 65 the electric motor of the machine to rest.

The accounting machine.

The accounting machine, generally indicated by reference numeral 500 (Fig. 1) comprises a number of identical units, depending upon the size of the machine. The 70 units are placed side by side and each comprises a pair of cheek plates 501, suitably spaced apart for the reception therebetween of the various mechanisms of the unit. These cheek plates 501 are carried on supporting brackets 502 mounted upon the 75 accounting machine base 95.

The terminal pin box.

Supported on the inner face of the 80 brackets 502 are the spaced hanging plates 504 (Figs. 2 and 25) between which are mounted pairs of cross supports disposed parallel to each other and transverse to the cheek plates. A terminal box 506 supported between said cross supports comprises side plates 507, inner pin guide plates 508 and lower pin guide plates 509. Between the cross-supports 505 are secured the 85 fixed terminal plate 510, held in place by 90 the upper and lower retaining plates 512 and 513 secured to the inner face of the cross-supports. The upper retaining plate is inwardly offset at 515 to provide a space 95 for receiving and supporting the lower edge of the terminal box.

The flexible connections or connecting cables 275 have their outer casings fixed to 100 said terminal plate 510.

To the upper ends of the inner wires of the connecting cables 275 are secured the 105 rows of terminal pins 518 each guided to vertical movement in the pin guide plates 508 and 509. Each terminal pin is provided with a restoring collar 519 normally resting 105 on the lower pin guide plate.

Disposed between the rows of terminal pins and resting on the restoring collars are the restoring bars 520, to the opposite 110 ends of which are secured the end pieces or supports carrying at their lower part the lifting rod 522.

When the wires of the connecting cables 275 are actuated the terminal pins 518 are raised, after which it is necessary that they again be lowered. This is accomplished by means of the Y-lever 524 fulcrumed upon the bracket 525 secured to the base 95. The outer end of the Y-lever is pivotally connected to the lifting rod 522 and has an 120 upwardly projecting cam-engaging arm 527 provided at its upper end with a roller 528 engaging in the peripheral cam groove 529 of the cam wheel 530 (Figs. 28 and 31) mounted upon the cam shaft 531 carried 125 in the cam shaft brackets 532 (Fig. 1) mounted upon the machine base 95. This Y lever is yieldably held in position with the roller in engagement with the cam by means of a spring 535 tensioned between the

free end 536 of the lever and the machine base 95.

The cam shaft 531 is positively driven from the cam shaft 59 by means of a connecting shaft 538 (Fig. 1) which may be operatively connected to the cam shafts 59 and 531 by means of usual bevel gears or other means of connection, whereby the cam shaft 531 is constrained to rotate in step with the cam shaft. The peripheral cam groove is so located and timed that the terminal pins 518 are lowered once during each revolution of the cam shaft and after the cooperating mechanisms have had time 10 to act as will be explained.

The rack bar positioning mechanism.

Above the terminal pins 518 of each unit there are located the upper and lower stop 20 guide plates 540 and 541 (Fig. 24) each provided with a plurality of rows of perforations. Rows of numeral stops 542, one stop in each row for each numeral from 1 to 9, are guided in these guide plates in 25 alinement with the terminal pins 518 as shown in Fig. 25. Each numeral stop is provided with a rearwardly and downwardly inclined upper face 543 (Fig. 39), a pair of upper and lower latching notches 30 544 and 545 in the sides thereof, a small projection 546 between the notches, and with a restoring notch 547 in the lower part of the stop.

Associated with each row of numeral 35 stops, adjacent to the stop corresponding to the numeral "1," is a zero stop 550 vertically slidable in the upper and lower guide plates and provided with an inwardly and downwardly beveled upper face 551, an outwardly 40 and downwardly inclined cam shoulder 552, and a horizontal resting face 553 adjacent to said shoulder. The zero stop 550 is also provided in the side thereof with upper and lower latching notches 555 and 556 (Figs. 23 45 and 35) of a small projection 557 between said notches. A pin receiving recess 558 is provided in the outer edge of the zero stop. Shutter supporting plates 559 are supported 50 between the cheek plates 541 by means of the shouldered projections 560 engaging appropriate slots in the cheek plates 501. These shutter plates are secured to and support the upper and lower guide plates 540 and 541. Between the supporting plates 559 are pivotally mounted shutter latches 561 (Fig. 38) 55 provided with pivot projections 562 engaging in suitable perforations 564 (Figs. 36 and 37) in the supporting plates. Shutter latches are each provided with end projections 60 561 and are disposed between the rows of stops and are provided with inturned edges 566 adapted to engage in the notches 544, 545, 555 and 556 of the stops. Each shutter latch is also provided with an end 65 projection 567 projecting through holes 568

in the adjacent supporting plate and engaged by springs 569 (Fig. 37) supported in small slots in the spring supporting plate 570 carried upon the shutter supporting plate 561. These springs hold the shutter latches in yieldable engagement with the latching notches.

Between the rows of stops 542 and 550 are disposed depressing levers 572 (Fig. 24) fulcrumed at their rear ends on the fulcrum rod 573 and provided with lateral projections 574 engaging in the depressing notches 547. The forward end of each depressing lever is provided with a headed lateral pin 576 engaging in a slot 577 of the connecting lever 578 intermediately fulcrumed on the fulcrum rod 590 and provided at its inner end with a headed lateral pin 591 engaging in said pin engaging recess 558 of the zero stop. Whenever a stop 542 is raised by 85 means of a terminal pin 518, the lower bevel face of the upper latching notch (Fig. 39) will engage the inwardly bent edge 566 of the latching shutter and force the same away from the latching notch 555 of the zero stop 90 550, whereupon the depressing lever 572 is raised and the inner end of the connecting lever 578 and the associated zero stop are lowered because of the positive engagement with the lateral projections 574, of the lower 95 part of the restoring notch 547 of the raised stop and also to an extent because of the influence of the spring 593 (Fig. 24) tensioned between the hooked cone plate 594 and the upwardly disposed hook 595 carried upon 100 the depressing lever 572. During this movement the projections 546 of the numeral stops will push the shutter latches so far that the upper latching notch 555 of the zero stop will surely be released for the projection 557 of the zero stop to surely cam over the shutter latch to permit the zero stop to be lowered.

The object of the raising of the numeral stops is for the positioning thereby of the 110 type-sector-operating reciprocating rack bars presently to be described. After this positioning has taken place, the numeral stops are restored as will now be described.

Vertically slidably secured on the outer 115 face of one of the side plates 507 (Figs. 25 and 27) is the restoring plate 597 provided with inwardly projecting pins 598 engaging in elongated slots 599, whereby said restoring plate is loosely connected to said terminal box for vertical movement. Intermediately upon the restoring plates there are disposed a pair of ears 600 supporting a cross rod 601 loosely received in an end slot 602 provided in the end of a restoring lever 120 604 intermediately fulcrumed on an ear 605 formed on the edge of the upper guide plate 508. The opposite end 606 of said restoring levers is pivotally connected to a curved link 125 608 pivotally connected to the lifting rod 130

522, whereby when said rod 522 is raised, the restoring plate 597 is lowered so that the zero stop 550 may be lowered if one of the terminal pins and the numeral stops alined therewith be raised. After the above mentioned positioning of the rack bars takes place, the lifting rod 522 is lowered bringing with it the restoring bars 520 and the terminal pins, at the same time through the intermediary of the curved link 608 and the restoring levers 604 raising the restoring plate 597 and thus lifting the zero stops, which are disposed directly over the restoring plate. This lifting of the zero stops raises the inner end of the connecting levers 578 thus lowering the depressing levers 572 and causing the lateral projections 574 to engage the lower part of the restoring notches 547 and positively to lower the numeral stops. The raising of the naught stops thus described forces back the shutter latches because of the engagement of the lower face of the latching notch 555 therewith, thus forcing back the shutter latches and releasing the same from the latching notches 554 of the numeral stops thus permitting the numeral stops to be lowered as explained.

From the foregoing, it will be apparent that when a perforated card is fed between the analyzing plates of the analyzer and analyzed therein, numeral stops corresponding to numeral perforations in the card will be raised at the same time that the zero stop associated therewith is lowered. If, however, in any column a zero perforation appears, there being no numeral perforation in that same column, there will be no numeral stop 542 raised, but the zero stop 550 associated with that same column will remain in raised position.

The reciprocating rack bars.

Associated with and slidably disposed above each row of numeral stops 542 is a reciprocating rack bar 610 (Fig. 24) slidable in the slots of cone plate 611 and the hooked cone plate 594. Each rack bar is provided at its intermediate part with an abutment providing an inwardly disposed shoulder 612. The outer end portion of each rack bar is provided with a longitudinal slot 614 receiving a cross rod 615 limiting the movement of the rack bars and holding the same in place. The inner end of each rack bar is provided in its upper edge with a plurality of rack teeth 616 adapted to engage the teeth of the gear wheel 617 secured to the type sectors 618 rotatably mounted upon the type sector shaft 620 mounted between the cheek plates 501.

The type sectors.

The type sectors 618 are provided with an arcuate portion 621 (Fig. 48) connected to the main portion of the type sector by means

of connecting pieces 622. This arcuate portion is provided with a plurality of outer notches 624 and inner notches 625 receiving the outer lug 626 (Fig. 50) and the inner lug 627 formed on the side of the type piece 70 628 carrying the numeral type 630 and secured by the rivets 631 to said arcuate portion as shown in Fig. 24. The type sector also has secured thereto a zero type 634 in a manner which will be explained. The 75 type 630 adjacent to the zero type 634 is the unit type, the remaining type bearing the designations 2 to 9, the 9. type being most remote from the zero type.

An abutment lever 635 is pivoted at its 80 inner end to the inner end of each rack bar and is provided intermediately with a horizontal pin receiving slot 636 and an abutment carrying an outwardly disposed shoulder 638 adapted to be spaced from 85 and passed to said inwardly disposed shoulder 612 of the rack bar. The outer end of the abutment lever is formed into an outwardly disposed extension 640.

Upon the outer end of each rack bar 610 90 is disposed an outer end standard 641 at the upper end of which is pivotally mounted a holding pawl 642 provided at its inner end with a hook 643. Between the hook 643 and a hook 645 carried upon the extension 640 95 is tensioned a spring 646 adapted to hold the extension 640 and the abutment lever in raised position and to hold the outer end of the holding pawl 642 in raised position.

There is provided a transverse drive bar 100 647 (Fig. 24) adapted to reciprocate back and forth in the drive bar slot 648 in the cheek plates 501, and adapted to be disposed between the shoulders 612 and 638, when the abutment levers are in raised position under the influence of the spring 646. This transverse rack bar is reciprocated back and forth by means which will presently be described.

Pivotedly mounted to each rack bar is an 110 elbow device 650 pivoted at its elbow part to the rack bar and provided with a downwardly extending arm provided with an upper inner shoulder 651 adapted to engage said cam shoulder 552 of the zero stop 115 when the zero stop is raised and to engage any raised numeral stop in the row with said zero stop, when the abutment lever is raised so that the upwardly disposed shoulder 638 120 is engaged and driven inwardly by the transverse drive bar. Said elbow device is also provided with an inwardly disposed arm 653 provided with a laterally projecting pin 654 adapted to engage in the longitudinal slot 636 of the abutment lever. 125

When the abutment lever is raised under the action of the spring 646 the transverse drive bar 647 engages the shoulder 638 and, when it moves inwardly, forces the abutment lever and its supporting rack bar in- 130

wardly until the abrupt shoulder 651 of the elbow devices engages the cam shoulder 652, if no numeral stop is raised, or a raised numeral stop. When this engagement takes place, the elbow device is rocked and the laterally projecting pin 654 lowered until the shoulder 638 is depressed enough to clear the transverse slide bar 647 and permit the transverse bar to move free, thus leaving the rack bar positioned by the raised stop in accordance with the perforation which brought about the raising of such numeral stop. When the rack bar is thus positioned, the type sector in mesh therewith is positioned so that the numeral type 630 corresponding to the raised numeral stop will be positioned in printing position as explained in the description of the printing carriage which is as follows:

20 *The rack bar reciprocating mechanism.*

The ends of the drive bar 647 project through the head 648 (Fig. 24) and are secured to the slide bars 657 (Fig. 22) slidable upon the outside of each cheek plate.

The outer end of each slide bar is provided at its inner face with a supporting roller 658 adapted to roll in the slot 648. The inner end of each slide bar slides between a pair of spaced rollers 658 rotatably mounted upon the outer face of the cheek plate, and is provided with a headed lateral pin 660 engaging in the upper end slot 661 of the drive lever 662 fulcrumed at 663 to 35 the lower part of the cheek plate. The lower end of the drive lever is provided with an inwardly projecting arm 665 (Figs. 24 and 30) provided at its rear end with a roller 667 engaging in the drive cam groove 668 40 in the cam 670.

The type sector holding and alining mechanism.

When the rack bar is positioned by means 45 of the engagement of the abrupt shoulder 651 (Fig. 24) or with a raised numeral stop, the numeral stop merely prevents the rack bar from moving forward but does not prevent retrograde motion which might take place on account of the unbalancing of the type sector on account of the weight of the arcuate portion 621. Now will be described means for preventing this retrograde movement. An inverted U-shaped bracket 683 50 is vertically slidably disposed between the outer ends of the cheek plates and comprises an intermediate horizontal yoke 674 and downturned arms 675, the lower ends of which are each provided with a vertical slot 676. A movable guide rod 678 is passed 55 through the upper part of said arm and through vertical slots 679 for guiding the upper part of the arms. A lower fixed guide rod 680 passing through the cheek plates is received in the vertical slots 676 for

guiding the lower part of the arms. A ratchet plate 682 is secured to said yoke and is provided in its lower face with ratchet ribs 683 disposed transversely relative to the cheek plates and providing inner abrupt shoulders 684 and outer inclined faces 685, said faces being adapted to be engaged by the outer end of the holding pawl 642 so that the holding pawl will cam over said faces when the rack bar moves inwardly. After the rack has moved inwardly and has been positioned by a raised numeral stop, the outer holding pawl 642 engages one of said abrupt shoulders, and holds the rack bar against retrograde movement.

80 After the rack bar is thus held against retrograde movement, the type sectors are locked in position by means of the locking and alining bar 687 disposed parallel to the type sector shaft 620, and provided with 85 projecting ends 688 (Fig. 22) slidable in the radial slots 690 in the cheek plates 501.

When this bar moves inwardly toward the type sectors, its lower beveled edge 691 engages between the gear teeth 693 of the type 90 sectors, whereby the type sectors are locked in alining position. This bar is reciprocated in the radial slots by means of alining links 695 secured to said reduced ends 688 and provided with a bifurcated lower end 696 95 embracing said cam shaft 531. A cam roller 697 is provided on each alining link 595 and engages in the alining cam groove 698 of the alining cam 700 (Figs. 28 and 33). As

shown in Fig. 28, there are two alining links 695 which are inwardly offset so as to pass between the cams 670 and 700. The cam groove 698 shown in Fig. 33 is provided in the cam 700 in which groove one of the rollers engages. The adjacent face of the cams 670 is provided with a groove of the same conformation as the groove 698 and in which the other cam roller 697 engages. The links 695 are additionally guided by the lateral pins 701 movable in the slot 701' in the 100 cheek plates. The locking and alining bar holds the type sectors in locked position until after the printing has taken place. And after the type sectors have been unlocked the ratchet plate 682 is raised for releasing 105 the holding pawl 642 and the abutment levers 635 are lowered, after which the transverse drive bar 647 returns to its initial position, engages the inwardly disposed shoulder 612 of the rack bars and returns the rack 110 bars to their initial position. The raising of the ratchet plate is accomplished by means of the lifting lever 702 (Fig. 24) intermediate fulcrumed at 703 to the inner face of the cheek plate. The outer end of the lifting lever is provided with an end slot 704 loosely receiving the headed pin 705 carried upon the downwardly extending arm 75. The inner ends of the lifting levers are provided 115 with end slots in which are received the op-

120

125

posite ends of the depressing rod 707 vertically slideable in the slots 708 in the cheek plates. To the ends of this rod are fixed the upper ends connecting links 709 having their lower ends secured to the lower rod 710 slideable in the lower slots 711 of the cheek plate. The lower rod 710 is received in the outer end slots 712 of the intermediate lever 714 intermediately fulcrumed at 715 (Fig. 22) 5 on the outer face of the cheek plate. The inner ends of the intermediate levers are loosely connected to the outer ends of the cam levers 716 (Fig. 33) pivotally connected as at 718 on the inner face of the cheek 10 plates. The rear ends of the cam levers are provided with the cam engaging rollers 719 engaging in the cam slot 698 of the cams 770. After the type sectors are unlocked, the cam-lever 716 is actuated to cause the depressing of the depressing rod 707 which thus engages upon the extensions 640 and lowers the abutment levers and consequently the abutments carrying the shoulders 638, thus permitting the transverse drive bar 647 15 to engage the inwardly disposed shoulder 612. The same movement which lowered the depressing rod 607 also raises the outer end of the lifting lever 702 and raises the ratchet plate 682, thus disengaging the ratchet plate 20 from the holding pawl 642 and permitting the rack bars to be moved by the transverse bars 647 to their initial position.

The accumulator carriage.

35 The accumulator cooperates with the teeth 693 (Fig. 24) of the type sectors to transfer to the accumulator the items set up by the type sectors.

40 The accumulator carriage 725 comprises a pair of spaced guide plates 726 (Figs. 45 to 47), each provided with a guide slot 727 at its outer end and an upper slot 728 at its upper part. A releasing rod 730 fixed between said cheek plates and received in said lower guide slots, and a fixed fulcrum rod 731 received in said upper guide slot guide the accumulator carriage in its reciprocatory movement. In addition to the above, further guiding means is afforded by the actuator shaft 733 fixed between the lower 45 part of said spaced side plates, and adjacent to said gear teeth 693, and projecting beyond the cheek plates. The outer ends of said accumulator shaft are provided with bearing sleeves 735 held in place by nuts 736 on the ends of the accumulator shaft.

The accumulator.

Upon the accumulator shaft between the bearing sleeves are disposed a plurality of 50 shouldered bushings 737 on which are disposed the accumulator gear wheels 738 each provided with ten teeth adapted to mesh with the gear teeth of the type sector. Secured to each accumulator wheel and rotatable on said bushings are the actuating

55 cams 740 each provided with a rounded projection 741 (Fig. 47) and a triangular projection 742 providing a radial face 743 and an inclined forward face 744, the object of which will be explained.

70

Two - action accumulator reciprocating mechanism.

While the machine is accumulating, the accumulator carriage is reciprocated and held away from the type sector teeth during the active stroke of the rack bars which brings the type sectors to printing position and are moved into and held in engagement with the type sector gear teeth during the 80 return stroke of the type sectors and rack bars. On the other hand, when a total is taken, the accumulator wheels are held in engagement with the type sectors during 85 the positioning stroke of the type sectors and are moved out of engagement therewith on the return stroke. Means are provided for imparting to the carriage these different actions, one when accumulating as above described, and the other for the taking of 90 totals. The reciprocating mechanism comprises a pair of actuating levers 747 (Figs. 22 and 40) having their upper ends embracing said bearing sleeves 735 and each comprising an upper element 748, and a 95 lower element 749 pivoted to each other at 750. The lower element is provided with a slot 751 in which engages a projection 752 carried on the upper element for limiting the pivotal movement between the elements. 100 Springs 754 disposed between the rearwardly disposed hooks 755 on said elements yieldably hold the upper elements at one limit of their movement relative to the lower elements. The lower elements 749 are each inwardly offset at 757, to form spaced locking plates 758, each provided with ears 760 which are secured together by the rivets 761 for holding the locking plates in spaced relation. Each locking plate is provided with 105 a central opening 763 (Fig. 41) each surrounded by a cam engaging sleeve 764 and 765. The lower elements 749 are fulcrumed on a fulcrum rod 766 mounted between the cheek plates 501. Disposed between the locking plates 758 and fulcrumed upon the fulcrum rod 766 between the actuating levers, are accumulating levers 767 and a total taking lever 768 intermediately spaced apart 110 and having intermediate cam engaging openings 770 and 771 disposed between said spaced locking plates and adapted to be aligned with said central openings. The rear end of the accumulator lever is provided with a cam engaging lever 773, engaging in the accumulating groove 775 in the cam 670. The rear end of the total taking lever is provided with a cam engaging roller 776 (Fig. 28) engaging in the total taking groove 115 777 of the cam 700 (Fig. 32). By reference 120

778 of the cam 700 (Fig. 32). By reference 125 779 of the cam 700 (Fig. 32). By reference 130

to Fig. 32, it is noted that the cam grooves 775 and 776 are approximately diametrically oppositely disposed so that the accumulating lever and the total taking lever are reciprocated in cycles of similar form but approximately 180° apart. Therefore, if the accumulating lever 767 is locked to the actuating levers, the carriage will be reciprocated in accordance with the total taking groove 775 (Fig. 32). On the other hand, if the total taking lever 768 be locked to the actuating levers, the accumulator carriage will be reciprocated in accordance with the total taking groove 777. The means for bringing about this locking comprises an assembling rod 779 (Fig. 41) on which are assembled the total taking cams 780 one for each unit of the accounting machine. Each total cam 780 is provided with an accumulating locking cone 781 and a total locking cone 782 forming therebetween a reduced portion 783. The total cams are held against excessive lateral movement in one direction of a limiting collar 784, the similar collar (not shown) being provided at the opposite side of the machine. The total cams are otherwise supported merely by being held in the sleeves of the locking plates 758.

The total shift mechanism.

When the total cam is shifted to the position of Fig. 41, the accumulating lever 767 is locked to the actuating levers and the actuating levers receive their reciprocatory motion therefrom. When the total cam is shifted to the position of Fig. 42, the total taking lever 768 is locked to the actuating levers and imparts this reciprocatory motion to the actuating levers during which period the accumulating lever is permitted to reciprocate idly in the space formed by the reduced portion 783 between said cones. Bringing about this shifting motion there is provided a total shift lever 785 (Fig. 43) bifurcated at its forward end to provide tines 786 adapted to engage in an annular groove formed between the end of the total taking cam 780 and a collar 787 (Fig. 41) secured on the end of the assembling rod 779. The rear end of the total shift lever is fulcrumed on a pivot post 788 (Fig. 1) mounted upon the base 95. Secured below and spaced from the total shift lever is the supporting plate 790 provided with downturned ends 791 and 792 and spaced from the total shift lever by means of spacing posts 793. Between the lever and the supporting plate is secured a spring housing 795 in which is slidably disposed a plunger 796 provided with a plunger head 797 passing through the shift lever and engaging in the shifting groove 798 of the shifting cam 530 (Fig. 28). The plunger is yieldably moved into said engagement by means of a spring 800 (Fig. 43) disposed in said hous-

ing and compressed between the supporting plate 790 and collar 801 carried at the lower end of the plunger head. The plunger is normally held out of engagement by means of an elbow pawl 802 pivotally mounted upon the bracket 803 carried on the supporting plate and provided with an end projection 804 adapted to snap behind the retaining head 805 on the plunger 796 under the influence of a spring 797 strained between said elbow pawl and the downturned arm 792. The downturned arm 791 carries a terminal block 806 on which is secured the outer casing of a flexible connection of the total cable 314 leading from the designation 80 change sensing mechanism. In this terminal block is also secured the end of the total cable 373 leading from the total card operated total mechanism illustrated in Fig. 2.

When a total is to be taken, the terminal pin of the inner wires of one of these cables 314 or 373 operates the elbow pawl 802 releasing the retaining head 805 whereupon the plunger is thrown into the shifting groove 798. This shifting groove is spiral in form (Fig. 28) and causes the total shift lever to shift outwardly, moving the total cam 780 from the position of Fig. 41 to the position of Fig. 42, thus releasing the accumulating lever 767 from the actuating levers and rocking the total lever 768 therewith, thus reciprocating the accumulator carriage for taking totals. At the end of the rotation of the shifting cam 530, the beveled abutment 793 forming the end of the cam groove engages the plunger head and forces the retaining head 805 back over the projection 804 whereupon the said projection snaps under the retaining head and holds the plunger in retracted position until the next total is taken.

The transfer or carrying mechanism.

Between the side plates of the accumulator carriage is carried the transfer or carry over mechanism of the accumulator for moving each accumulator wheel one tooth space when the accumulator wheel of the next lower order has moved ten tooth-spaces or one complete revolution. This mechanism comprises a plurality of settable levers 807, intermediately fulcrumed on the fulcrum rod 808 mounted between the said plates of the carriage. Each settable lever is provided with a hooked inner end 809 adapted to engage said radial face 443 and to be engaged and lifted by the inclined face 744 when the projection 742 makes a complete revolution. At the outer end of the accumulator carriage is disposed the detent rod 810 on which are fulcrumed the detent 811 having a hooked upper end 812 adapted to engage over the outer ends of the detent levers 807, when the accumulator car-

riage is reciprocated inwardly and when the corresponding settable levers are rocked by the raising of the inner end 809. The lower arms 815 of the detent levers are adapted to engage the guide rod 730 when the accumulator carriage is reciprocated outwardly, whereupon the detent levers are moved to the position of Fig. 47 against the action of the spring 816 strained between the hook 10 817 on the detent lever and the hooks 818 carried by the comb plate 819, between the teeth of which are held in spaced relation the settable levers 807 and the detent levers 811. When this releasing takes place the 15 inner end of the settable levers are drawn down by means of the spring 821 strained between the inner end of each settable lever of the hook plate 822 mounted between the side plates of the carriage.

20 Fulcrumed to the inner face of each of the respective side plates is a restoring lever 824, fulcrumed at 825, and provided at its outer end with a lower cam face 826 adapted to be engaged by the restoring rod 827 mounted 25 between the cheek plates 501 for raising restoring levers when the accumulator carriage is retracted outwardly. Between the restoring levers is carried a supporting rod 829 from which hang the pendant links 830 30 provided with upper end slots 831 receiving said supporting rod. The upper portion of these pendant links are also provided with laterally turned lips 832 adapted to engage over the associated settable levers and to hold the pendant links in raised position 35 when the settable levers are in the position of Fig. 47, but to permit the pendant links to be drawn down under the action of the springs 834, when the inner end 809 of the 40 settable levers are raised by the cam face 744. To the lower end of each pendant link 830 is pivotally connected the outer end of a carrying bar 836, the forward end of which bar is pivotally connected to the lower end 45 of the carrying lever 837 fulcrumed on the fulcrum rod 731 at the upper part of the accumulator carriage. The lower end of the carrying lever is yieldably held inward by means of a spring 838 strained between the 50 hook 839 of the carrying lever and the hook plate 840 carried between the side plates of the carriage. A spring 841 strained between said hook plate 840 and a hook 842 on the rear end of the restoring levers 824 yieldably 55 holds the outer ends of the restoring levers in depressed position. The cone plate 843 holds the rear part of the settable levers of the kick back levers in spaced relation. The outer end 845 of each carrying lever is 60 provided with a cam engaging roller 846 adapted to be engaged by one of the stepped cams 847 of the carrying cam plate 848, supported on rollers 849 (Fig. 42) engaging in the guide slots 850 in the cheek plates 501.

65 This cam plate is reciprocated inwardly

after by the mechanism which will presently be described, after the item set up by the type sectors have been transferred to the accumulator wheels. When the carrying bar 836 is raised in Fig. 47 it does not come in contact with the inwardly turned shoulder 612 of the reciprocating rack bars, but when the settable levers are rocked and the pendant links and the outer end of the carrying bar lowered, the carrying bar is in position 75 to engage the shoulder 612, when the lower part of the carrying lever 837 is rocked outwardly through the action of the cams 847.

The carrying cam reciprocating mechanism. 80

For reciprocating the cam plate 848 there are provided a pair of reciprocating racks 852 (Fig. 23), one on each side of the accounting machine unit, secured at their inner ends to the cam plate and provided at the lower edge with rack teeth 852 adapted to be engaged by the pinion 853 supported upon a pinion spindle 854 passing through both pinion slots 855 in the cheek plates 501. Beneath each pinion and meshing therewith is 90 a fixed rack 857 secured to the outer face of the cheek plate. Fulcrumed as at 858 to the outer face of each cheek plate is a spindle drive lever 859 provided with an upper end slot 860 receiving the spindle 854. The 95 lower end of the drive lever is provided with a bifurcated lower end forming a lower end slot 861 receiving therein a drive rod 862 resting on the smooth supporting face 863 (Fig. 22) carried on the base 95. To the 100 drive rod 862 are secured at opposite ends the drive links 864 provided at their rear ends with a slot 865 receiving the cam shaft 531. Said drive links 864 (Figs. 28 and 29) are provided at their rear ends with rollers 105 866 adapted to engage in the carrying cam groove 867 of the shifting cam 530 and the additional cam wheel 870.

For preventing the accidental rotation of the accumulator wheels when they are out of mesh with the type sectors, there is provided an alining rod 873 (Figs. 24 and 47) carried between the lower ends of the supporting levers 874 intermediately fulcrumed, as at 875, to the side plates 726. When the carriage is reciprocated inwardly, the rod is kept out of engagement with the accumulator teeth by engagement with the lug 878 (Fig. 22) formed on the upper edge of the cheek plates 501.

When the accumulator carriage is retracted, the rod 873 is yieldably held between the accumulator teeth by the spring 879 strained between the upper end of the lever 874 and the comb plate 880. A comb plate 881 (Fig. 125 47) having angular teeth 882 holds the kick back bars 836 in spaced relation.

The carrying operation.

Considering the accumulator wheels to be 130

in zero position as shown in Fig. 48, any item that is set up by the type sectors rotates the associated accumulator wheel in a direction which is clockwise of Fig. 47, when the type sectors are returning to their initial position.

As there will be no individual digit greater than 9, there will be no complete revolution of the accumulator wheel when 10 the first item is set up. If there should be an additional item set up which added to the previous item gives a number greater than 10, the accumulator wheel will rotate more than one revolution and in so doing, 15 the cam face 744 will engage the inner end 809 and rock the associated settable lever 807, causing a lowering of the associated pendant link 830 and the associated carrying bar 836, in turn associated with the 20 shoulder 612 of the rack bar of the type sector and accumulator wheel of the next higher order. When this rocking of the settable lever takes place, the detent lever 811 engages over the outer end of the settable 25 lever and holds the same in set position until the cam plate 848 is reciprocated inwardly and engaging the rollers 846 rocks the kick back levers so that the kick back bars 836 are moved outwardly. These 30 carrying bars which have been lowered as thus explained will, during this outward movement, engage the shoulder 612 of the rack bar of the next higher order, and thereby rotate the type sector and the associated 35 accumulator wheel of said next higher order, one tooth space, so as to add thereto one unit, which thereby effects the carrying. After the carrying has been effected, the 40 accumulator carriage moves outwardly bringing the lower arm 815 of the detent levers into engagement with the releasing rod 730 whereby the settable levers are released and resume their normal position against the action of the spring 821. At the same time 45 the cam face 824 of the restoring levers engages the restoring rod 827 and thereby raises the pendant links 830 of the carrying bars 836. When the cam plate 848 again reciprocates outwardly, the carrying levers 50 are restored to their normal position under the influence of the spring 841.

The cams 847 are placed in stepped relation with the cams of the lowest order nearest to the rollers 846 so that the lowest orders 55 will be actuated first, so that if the actuation of a carrying roller and bar of a lower order should be effected by this cam engagement, carrying would take place which might move the accumulator wheel of the next higher 60 order past the carrying point, in which case the cam of the next higher order not having yet come into engagement with its roller, would subsequently come into engagement with its roller after the carrying bar associated therewith had been lowered and

therefore cause the carrying of its associated accumulator wheel.

Rack bar restoring mechanisms.

To prevent the accidental moving back 70 of the rack bars during carrying, when not positively driven back by the carrying bar, and to aid in restoring them, there is provided for each rack bar a spring pressed restoring slide 903 (Fig. 24) slidable between 75 the teeth of the inner and outer comb plates 904 and 905 mounted between the extension plates 906 carried at the forward edge of the cheek plates. The restoring slides each has at its inner end a laterally turned lip 80 907 adapted to engage one of the rack bars. The slides are spring pressed against the rack bars by means of springs 909 strained between hooks 910 on the inner comb plate 904 and hooks 911 carried on a downwardly extending arm 912 carried at the outer end of each slide. This arm serves to limit the inner movement of the slide.

After the rack bars have been kicked back during the carrying over, they are restored 90 by the restoring rod 915 carried between the upper ends of the restoring levers 916 intermediately pivoted at 917 on the inner face of the cheek plates. To the lower end of the restoring levers are pivotally connected the restoring links 919 in turn pivotally connected to the upper end of the vertically disposed levers 920 (Fig. 22) fulcrumed at their lower ends to said cheek plates and each provided intermediately 95 with a cam roller 921 adapted to engage in the peripheral cam groove 922 (Fig. 30) carried on the cam 670. After each carrying operation, this restoring rod is reciprocated inwardly thus restoring all the rack bars to 100 their normal initial position.

Total taking mechanism.

When totals are taken, the total taking cam is shifted so that the accumulator carriage is reciprocated into engagement with the type sectors on the initial stroke of the transverse drive bar 647 (Fig. 24) and the rack bars. At the commencement of this stroke the outwardly disposed shoulders 638 110 are in raised position and disposed against the inner face of the transverse drive shaft. It is desirable that this engagement should continue until the type sectors rotate the accumulator gears in anti-clockwise direction of Fig. 24 until the radial face 443 comes into engagement with the end 809 of the settable lever thus setting the type sectors in position for printing the total which has been accumulated by the accumulator. 115 When this initial movement of the rack bar is taking place, the naught stops 550 must be lowered, so as not to trip the elbow device 650, and at the same time the numeral stops 542 must remain down. This action 120 125 130

is accomplished by means which will now be described.

On the total cam 780 (Fig. 41) there is provided a shutter releasing cone 925 adapted when the cam is shifted to the position of Fig. 42 for taking totals to engage the shoulder retracting lever 926 fulcrumed on the fulcrum rod 573 (Fig. 24) and provided with an upwardly extending arm 927 having its free end passing to the outer face of the cheek plate (Fig. 22) and guided between the cheek plate and the end of a headed pin 928 projecting from the side of the cheek plate. This free end, when the lever is thus engaged, moves upwardly and engages the cam projection 929 projecting through a small slot in the cheek plate and carried on the shutter retracting plate 930, (Fig. 37). The shutter retracting plate is provided with a pair of guide slots 932 slidably receiving supporting pins 933 carried by the shutter supporting plate 561. A spring 934 strained between pins 935 carried on the shutter retracting plate and the shutter supporting plate respectively holds said shutter retracting plate with the cam projection 929 in outward position. The lower part of the retracting plate is provided with a plurality of downwardly projecting fingers 937 adapted to engage between the end projections 567 of the shutter latches, whereby when said shutter plate is pushed toward the right of Fig. 37 by the engagement of the arm 927 with the cammed projection 929, the shutters are retracted from the latching notches of the numeral stops and the zero stops, thus permitting the zero stops to be lowered by the downward movement of the rear end of the connecting lever 578, Fig. 24, and the upward movement of the depressing lever 572 under the action of the spring 593, the lateral projections 574 riding up in the long restoring notches 547 without raising the numeral stops. This action permits the rack bars during total taking to be driven forward as above explained without interference by any of the zero or numeral stops. This movement continues until the radial faces 743 engage the downturned ends of the settable levers, whereupon the rounded projections 741 engage the depressing rollers 940 carried on the vertically slidable roller brackets 941 held in spaced relation between the teeth of the comb plates 942 mounted between the cheek plates, and guided and limited in its movement by means of the guide rods 943 carried between the cheek plates and received in the vertical slots 944 of the roller brackets. When thus engaged, the rollers press downwardly and engage and depress the abutment levers 635 thus lowering the outwardly disposed shoulders 638, from engagement with the transverse bar 647 and permit the latter to pass

on. After this has taken place, the locking and alining bar 687 moves into engagement with the teeth 693 and holds the type sectors in alinement while the paper carriage presses the paper against the type. 70

The column cutout mechanism.

Very often it is desirable to cut out a column so that any particular line of digits will neither accumulate or print. This is accomplished by means of the mechanism shown at the right hand side of Fig. 24 and comprises means for holding both the type sector and its associated rack bar out of action. Disposed between the extension plates 906 secured to the rear part of the cheek plates, are the upper comb plate 950 and the lower comb plate 951, between the teeth of which are slidably received the column cutout bars 954 each provided at its upper part with an upper shoulder 955 and a lower shoulder 956, the upper shoulder 956 being adapted to engage over the same. A spring 957 strained between the upper part of the cutout slide bar and the hook plate 958 carried between the extension plates holds the shoulders 955 and 956 in yieldable engagement with the upper comb plate. The upper and lower retaining rods 960 hold the cutout bars between the teeth of the comb plates. The lower end of each bar 954 is provided with a laterally turned elbow 961 adapted to bear upon the rear extension 640 of the abutment levers, when the cutout plate is lowered with its shoulder 955 engaging under the upper comb plate, thus holding the abutment lever in depressed position. When the abutment lever is thus held depressed, the transverse drive bar 647 does not engage the outwardly disposed shoulder 638, but passes and the rack bar of which the abutment lever is thus held depressed, is not moved forwardly, and does not actuate the type sector nor the associated accumulator wheel, and therefore, does not effect either printing, accumulating or carrying. 95

The accumulator cutout.

Sometimes it is desirable to hold the accumulator accounting machine units entirely out of operation. This is easily accomplished by means of an accumulator cutout lever 965 (Fig. 22) fulcrumed at 966 to the outer face of the cheek plate, and provided at its inner end with a downwardly hooked end 967 adapted to engage over the sleeve 735 (Fig. 45) of the accumulator shaft, whereby the accumulator wheels are held against reciprocation and out of engagement with the type sectors, the lower element 749 of the actuating lever continuing to reciprocate against the tension of the spring 754 while the upper end of the upper element is held practically stationary. The outer end 968 of the cutout

lever is formed into a handle adapted for manual operation to shift the lever into or out of engagement with the said sleeve, the outer end being elastic enough to be bent 5 slightly outward so that it may be caught either above or below the projection 969 on the outer face of the cheek plate for locking the cutout lever in either operative or inoperative position.

10 *Total designating mechanism.*

Sometimes when a group of cards of the same group and all containing the same key or designation number are run through the 15 machine, it is desirable that this designation number also appear in the total. If this designation number were transferred to the accumulator each time an item is printed, the resulting total would show the 20 product of this designating number multiplied by the number of times it was printed. This product would of course be meaningless and it is not desired that it be printed with total; but it is desired that the key 25 number only be printed with the totals. This is accomplished by permitting the key number to be transferred to the accumulator only once, after which the accumulator is held out of action until the taking of the 30 total, at which time it is again thrown back into action so that this number which was transferred once to the accumulator is transferred back to the type sectors and therefore printed with the totals. This 35 mechanism is shown in Fig. 23 and comprises an anchor lever 970 fulcrumed to the cheek on the fulcrum pin 971 and provided with a hooked free end 972 adapted to engage over the sleeve 735 of the accumulator 40 shaft. The fulcrumed end of the anchor lever is provided with an upwardly disposed lug 974 providing a rearwardly disposed thrust face 975. There is a retracting lever 976 fulcrumed to the fulcrum pin 971 and 45 provided with a forwardly disposed thrust face 977 adapted to engage the thrust face 975. These thrust faces are yieldably held into contact with each other by means of a spring 978 strained between the hooks 979 50 carried on the lug 974 of the retracting lever 976 respectively. The upper end of the retracting lever has pivotally connected thereto a thrust bar 980 provided with a downwardly disposed projection forming a thrust shoulder 982 adapted when the outer end of 55 the actuating bar is disposed below the projection 983, to be struck by the lower part of the slotted extension 984 carried upon the upper end of the lever 859 and provided 60 with a slot 985 receiving said actuating bar and permitting vertical movement therein so that the actuating bar may be disposed above the projection 983 to hold the bar in such position that the shoulder 982 will not 65 be struck by the extension 984. The retract-

ing lever 976 is provided with an outwardly extending arm 986 provided with a laterally turned catch-lip 988 adapted to be engaged by an upwardly disposed shoulder 989 on the elbow latch 990 fulcrumed at 991 70 to the side of the cheek plate. A spring 993 strained between the arm 986 and the latch 990 yieldably holds the shoulder 989 in engagement with the lip 988, or holds the arm 986 in lowered position so that the anchor 75 lever is held out of engagement with the accumulator arm sleeve. The lower end of the elbow latch is provided with an inwardly disposed arm 995 adapted to be engaged by the outwardly disposed arm of the tripping elbow 996 fulcrumed at 977 to the outer face of the cheek plate and provided with a lower arm 998 adapted to be engaged by the designator cone 999 (Fig. 41) 80 of the cam 780. 85

The operation of the total designating mechanism.

The actuating bar 980 is adjusted below the projection 983 and the designating or 90 key number is, during the normal operation of the machine, transferred to the accumulator once before the shoulder 982 is struck by the slotted extension 984. When this striking takes place, the retracting lever 95 976 and its thrust face 977 are rocked inwardly, whereupon the arm 986 is raised permitting the shoulder 989 to snap under the lip 988 whereupon, as soon as the accumulator shaft moves outwardly, under 100 the action of the spring 978, the anchor lever 970 is also rocked downwardly and engages the accumulator shaft sleeve so that the accumulator is held out of operation. As the unanchored units of the machine 105 continue to accumulate, the accumulating carriage thus anchored back is continually held out of operation, after having had the designating or key number transferred thereto only once. When however, a total 110 is taken and the total cam is shifted from the position of Fig. 41 to the position of Fig. 42, the lower arm 998 of the tripping elbow is engaged thus actuating the tripping elbow and the elbow latch 990, thus 115 drawing the shoulder 989 out from under the lip 988 whereupon under the action of the spring 993, the arm 986 is drawn downwardly, thus raising the hooked end 972 and releasing the accumulator carriage and 120 permitting the accumulator, during the taking of the total, to transfer to the type sectors the designating number which was transferred thereto. As the machine continues to operate and the designating number 125 of the next card group is set up by the type sectors, this new designating number is transferred to the accumulator carriage, and the shoulder 982 is struck by the extension 985 thus latching up the arm 986, and when 130

the accumulator carriage moves back the anchor lever snaps down and the accumulator carriage is again held out of operation until the next total is taken in the same 5 manner as has just been explained.

The cipher cut-out mechanism.

In Figs. 51 to 64 is shown a cipher cut-out mechanism which has for its object to 10 provide a mechanism for preventing the printing of zeros before the numerical digit of the highest decimal order of a number. Pivotally mounted on each type segment 618 is a zero type support 1038, (Figs. 51 and 59), mounted upon a pivot pin 1039 held in non-printing position by means of a spring 1040 strained between a hook 1041 (Fig. 51) and a tail 1042 carried upon said zero support. The zero support is limited 15 in its retracted movement by means of a lug 1044 engaging against the edge of the type segment. Pivoted upon said pin 1039 is a roller carrying bracket 1046, (Fig. 56), provided with a pair of recesses 1048 and 20 1049 in either of which the zero type 634 carried on said support may be engaged. Each roller carrying bracket is provided with a small roller 1054 rotatably mounted upon 25 a pin carried in the side of the roller carrying bracket, said roller being adapted to be engaged by the roller engaging lug 1052 of the roller carrying bracket of the next higher order. There is also carried on each 30 bracket a cam engaging roller 1054 adapted 35 to be engaged by a cam 1055, (Fig. 55), secured to the type segment 681 of the next higher order. The metal of the roller carrying bracket and zero support is made elastic and the zero type may be removed from 40 either recess 1048 and 1049 and placed in the other merely by slightly separating said bracket and support by means of any pointed instrument such for instance as a pen-knife. When the zero type is placed in the recess 45 1049, the roller 1054 is held out of operative engagement with the cam 1055. A small lug 1068 carried on the bracket 1046 limits its movement relative to the zero support.

Just before a card is analyzed, the rack 50 bars are in retracted position as shown in Fig. 24. At this time, the type segments occupy a position shown in Fig. 51. When a card is analyzed, if there be no perforation representing numbers higher than zero, 55 as in the first item of sheet 1057, (Fig. 64), the numeral type take the position shown in Fig. 22. But a zero type position in the recess 1049 will not be removed to the printing position it occupies in Fig. 52 because 60 no cam 1055 will have moved far enough to engage the roller 1054. If, however, the segments of the lower order and segments of a higher order be moved only to the zero position, and a segment of an intermediate order be moved to print a numeral 65

greater than zero, as in the second item of Fig. 64, the cam 1055 of such intermediate segment will engage the roller 1054 of the zero positioned segment of the next lower order and draw the associated zero support 70 1038 down to zero printing position as shown in Fig. 52. The lug 1052 of the support thus drawn down will engage the pin 1051 of the roller bracket to its right, of the next lower order, which will in turn bring 75 down the next zero support and so on until the end of the series of zero positioned segments, unless some one of the roller brackets has been adjusted to inoperative position as will be further explained. 80

On the other hand, however, the zero support 1038 of the zero positioned segments of an order higher than said intermediate segment will not be brought down because the cam 1055 of a segment engages 85 the roller of the next lower order and not of a higher order, and nothing will be printed by the zero positioned segments of the orders higher than said intermediate segment. 90

If there be several intermediately zero positioned intermediate segments between numeral positioned segments of a higher order and of lower order, as in the third row of Fig. 64, the cam 1055 of a higher 95 order segment will bring down the zero support of the nearest of said intermediate segments and the lug 1052 of such zero support will bring down the next lower zero support and so on for all of said intermediately adjacent zero positioned segments until said numeral positioned lower order segments have been reached. Of these latter, the zero supports being, of course, moved out of reach of the lug 1052 of the 100 zero support of the zero positioned type segments. 105

Should it be desired to break the operative connection between any zero support and the elements of the next higher order, 110 the roller carrying bracket 1046 of such zero support will be moved until its recess 1049 receives the zero type 1050, in which case the roller 1054 and the pin 1051 thereof will be disposed entirely out of the paths 115 of the cam 1055 and the lug 1052 of the segment of the next higher order, as shown in Figs. 53 and 54, thus, as it were, dividing the printing element into three zones, in which case two items such as in the last 120 three rows of Fig. 64 could be printed. 125

In view of the above, it is obvious that any numeral positioned type segment of any zone will cause the drawing down, to zero printing position, of all of the zero type supports of all of the successively adjacent zero positioned type segments of that same zone; and that no numeral positioned type segment will effect the drawing down of a zero type support of a higher order. 130

If it be desired to print a decimal or other mark 1058 of separation between adjacent columns of the printed sheet 1057, this is done by means of the printing points 5 1059 (Fig. 63) of the decimal or separating plate 1060, which plate may be secured to segment 1038 by screws 1061 (Fig. 53). One or more of these plates may be placed wherever thought desirable, or omitted entirely. 10

Operation of the accounting machine.

The operation of the various mechanisms of the accounting machine have already been 15 given, and it is necessary to refer only briefly to the operation of the accounting machine as a whole.

The restoring bars 520 (Fig. 25) having been raised by the Y-lever 524, the side 20 plates 90 (Fig. 1) move backwardly to bring the terminal pins 270 (Fig. 11) against the extension pins, which, with the settable pins, have already been set by the operation of the analyzing pins, as has been explained, 25 whereupon the terminal pins 518 (Fig. 25) are raised under the action of the inner wires of the connecting cables 275. When the Y-lever is raised, the restoring plate 597 is lowered, and any raising of a terminal pin 518 causes the raising of a registering numeral stop 542. Thus, through the intermediary of the depressing lever 572 and the connecting lever 578, lowering the zero 30 stop associated with the corresponding row 35 of numeral stops. When the numeral stops are thus raised, the transverse rack bar 647 (Fig. 24) moves forwardly and engages the inwardly turned shoulder 638 of the abutment lever 635, which has been already 40 raised under the action of the spring 641. The rack bar and the abutment lever continue to move forward with the transverse bar 647 until the shoulder 651 of the elbow lever comes into contact with a raised numeral stop 542, or a raised zero stop if no 45 numeral stop of the same row has been raised. When this contact takes place, the elbow device 650 is rocked, thereby lowering the shoulder 638 and permitting the 50 transverse drive bar to move on. The rack bar thus stopped is held against retrograde movement by the engagement of the holding pawl 642 with the ratchet plate 682 thus positioning the rack bar. When the 55 rack bar is thus moved and positioned, the type sector 618 in mesh therewith is also moved and positioned a distance corresponding to the movement of the rack bar, thus positioning in front of the printing carriage later to be described, one of the type 60 630 or 634 of the type sector. When the type have been thus positioned, the alining bar 687 moves inwardly and engages between the type sector gear teeth 633 and 65 holds the types alined during the printing

operation. After the printing has taken place the alining bar 687 is retracted, the ratchet plate 682 raised, and the depressing rod 650 moves down against the extension 70 640 of the abutment levers thus lowering the abutment carrying the outwardly disposed shoulder 638, permitting the transverse drive bar 647 to return and engage the inwardly disposed shoulder 612, to restore the rack bars to normal position. Before this restoring movement, the accumulator wheels 738 move into engagement with the type sectors, and during the restoring movement, the accumulator wheels are rotated in a direction which is clockwise on 80 Fig. 24, thus transferring to the accumulator wheels any amounts that have been set up on the type segments.

If this movement of the accumulator wheel carries the wheel more than one revolution, the inclined face 744 (Fig. 47) engages and sets the settable lever 807, thus lowering the carrying bar 836 to a position in front of the inwardly disposed shoulder 612, after which the cam plate 848 moves 90 inwardly rocking the carrying lever 845 and causing the carrying bar 836 to kick back against the shoulder 612 of the rack bar of the next higher order, thus moving said rack bar and its associated type segment and 95 its accumulator wheel forwardly a distance of one tooth, whereby carrying is effected. If the carrying thus effected causes any accumulator wheel to complete one revolution, the inclined face 744 of that accumulator wheel sets its settable lever 807 which immediately lowers the carrying bar 836 of the next higher order, whereupon the cam face 847 of said next higher order, being the more remote from its roller 846, comes 100 into engagement with its roller after said carrying bar has been thus lowered and effects carrying of the accumulator wheel of the still higher order. After carrying has 105 taken place, the accumulator carriage is retracted and the settable levers and the carrying bars are restored because of the engagement, with the rods 827 and 830, of the restoring levers 824 and the detent levers 811. When as a result of the commencement 110 of a new card group or the presence of a total card in the analyzer, the cable 314 (Fig. 43) or the cable 373 brings about the release of the elbow pawl 802, the plunger 769 immediately flies into engagement with the spiral shifting groove 798 of the shifting cam 530 and causes the total cam 780 to move to the position of Fig. 42, thereby locking the actuating levers 747 to the total taking lever 768. This brings 125 about the reciprocation of the accumulator wheels into mesh with the type sectors on the initial stroke of the transverse drive bar 647. This movement of the total cam also actuates the shutter releasing lever 926 and 130

the shutter releasing plate 930 (Fig. 37) thus opening the shutter latches 561 and permitting the zero stops 550 to be lowered under the action of the spring 593 (Fig. 24). 5 When the stops have been thus lowered, the rack bars are free to move inwardly with the transverse drive shaft 647 until the radial face 443 moves into engagement with the downturned end 809 of the settable lever. At the same instant, the rounded projections 741 come into engagement with the depressing roller 940 and depress the abutment levers 635, permitting the transverse drive shaft to pass on. As in the case of 10 accumulating, when the rack bars are held against retrograde movement by the ratchet plate 682 and the type sectors are locked by the alining bar 687, the printing carriage brings the paper against the type and 15 prints the total.

The printing carriage.

The printing carriage, designated generally by reference numeral 1100 (Figs. 2 and 25 65) is located on the rear of the accounting machine base 95 to the rear of the accounting mechanism.

The carriage is supported, at opposite ends, on the cam shaft brackets 532 (Fig. 30 65) and the lever shaft brackets 1101 carried on the base 95. These brackets are tied together at their upper part by the tie plates 1102 (Fig. 66) bolted at opposite ends to the upper part of these brackets respectively.

The lever shaft brackets 1101 are provided at their upper ends with guide slots 1104 in which are received the L-shaped carried supporting brackets 1105 provided 40 at their forward ends with anti-friction rollers 1106 adapted to reciprocate in the elongated openings 1107.

The supporting brackets 1101 are formed near their rear ends with uprights 1108 between the upper ends of which are carried the rail supporting bar 1109. Between the rear ends of said supporting brackets is carried the arm supporting shaft 1110, intermediately of the ends of which are carried 50 the L-shaped supporting members 1112 comprising the forwardly extending carriage supporting arms 1114.

Intermediately of the ends of the supporting bar 1109 are carried the forwardly projecting tie plates 1115 which carry at their forward ends the carriage rail 1116.

The carriage proper comprises end plates 1117 held spaced apart by the tie rod 1113 and the bracket shafts 1129. On the bracket 55 shafts are mounted the rearwardly extending supporting brackets 1118 each provided with a circular opening adapted to receive the carriage rail 1116, this opening being provided with a rearwardly extending slot 65 1119 adapted to provide a passage for the

tie plates 1115 when the carriage is slipped onto the carriage rail. When the carriage has been put in place it is thus supported by said carriage rails and by the forward ends of the arms 1114 engaging under the tie rod 70 1113 at the lower forward part of the carriage.

Between the end plates 1117 is mounted the paper roller shaft 1120 carrying part of the paper supporting and feeding mechanism to be described more in detail thereafter.

The carriage locating mechanism.

In the operation of the machine it is sometimes desirable to shift the carriage relative to the type sector units, so that the printing columns may occupy various desired positions upon the sheet of paper. Means for accomplishing this will now be described:

The forward edge of the uprights 1108 (Figs. 66 and 68) of the brackets 1105 are provided with inwardly turned perforated ears 1121 carrying supporting studs 1122 on which are slidably mounted the locating 90 bar 1124 provided with elongated slots 1125 receiving said studs, said bar being also provided with a plurality of holes 1126 large enough to receive the heads of the locating stud 1127 fixed on the locating bracket 1128 95 fixed to the bracket shafts 1129 (Fig. 66) connecting the end plates 1117.

The carriage may be swung outwardly upon the rail 1116 (Fig. 65) until the stud 1127 clears the holes 1126, and the carriage 100 then shifted longitudinally until the stud engages in a different hole 1126, as desired. The stud 1127 and bracket 1128 are locked in the adjusted position by means of a locking plate 1130 provided with key slots 1131 105 each having a large end 1132 (Fig. 67) thru which the head of the stud 1127 is adapted to pass and with small ends 1134 adapted to form shoulders to engage under the head of said stud whereby the stud is 110 positioned by means of a spring 1135 tensioned between the upright 1108 and the angular manipulating end 1136 (Fig. 68) bent outwardly on said locking plate. The locking plate is held in proper position relative to the locating bar by means of a guide plate 1133 secured to an upright 1108 receiving one end of the locking plate and slotted guide plate 1133' secured to the other end 115 of the locking plate and embracing the screw 1134' in the ear 1121.

Carriage reciprocating mechanism.

The printing is accomplished by the forward movement of the paper supporting 125 mechanism which movement brings the paper against type 630 and 634 of the type sections 618. This is accomplished by means of the upper and lower carriage actuating levers 1137 and 1138 (Fig. 66), pivoted on the 130

lever shaft 1139 carried by lever shaft brackets 1101. The upper and lower actuating levers are both pivotally mounted on said shaft 1139 and when in printing position 5 are locked together as will be explained, and are oscillated by means of the engagement of the cam roller 1140 engaging in the cam groove 1141 of the printing cam 1142 carried on the cam shaft 531. The actuating 10 levers give one complete cycle of oscillation once for every revolution of the cam shaft 531.

This locking is accomplished by means of locking cones 1145, which are shown in unlocked position in Fig. 67, and must be 15 moved to the right of said figure to lock said upper and lower levers against relative movement. These cones engage in, and when locked, hold in alignment the openings 20 1148 and 1149 of said upper and lower levers, and are carried on the cone supporting shaft 1150 yieldably drawn to unlocked position by means of the tension spring 1151 secured between the end of said shaft and a 25 cross piece 1152 (Fig. 66) disposed across the opening 1154 in the lever bracket 1101. The opening 1154 is large enough for the insertion of the cone shaft and cones when assembling the machine. These cones may 30 be moved to locking position by means of the bell-crank lever 1155 fulcrumed on the base 95 of the machine and provided at its upper end with spaced ears 1156 engaging a transverse pin 1157 in the cone supporting 35 shaft 1150. This lever is actuated by means of a link 1158 pivoted at its lower end to the motive arm of said lever, and at its upper end to the locking lever 1160 (Figs. 1 and 66) fulcrumed intermediately as at 1161 on 40 the cam shaft bracket 532. The locking lever 1160 terminates in a manipulating end 1162 (Figs. 1 and 74) received in a slot 1164 of the locking plate 1165, said slot being provided at its upper and lower parts with 45 shoulder forming recesses 1166 and 1167 in which said manipulating end may be locked to retain said locking cones in either locked or unlocked position.

50 *The paper supporting means.*

On the paper roller shaft 1120 journaled in the end plate 1117 (Figs. 65 and 73) are disposed a plurality of paper rollers 1248 each provided with a boss 1249 held spaced 55 apart by means of spacing bushings 1150 (Fig. 72). Between adjacent pairs of the paper rollers and loosely engaging said bushings are disposed platen support brackets 1251 held against rotation by means of 60 the bracket shaft 1252 passing thru perforations in the lug 1254 on the upper part of said brackets, said brackets being held in spaced relation by means of sleeves 1255, (Fig. 51), carried on said shaft 1252. The 65 lower part of each platen support bracket

carries a forward projection 1254 on which is secured, as by means of a screw 1256, the platen support 1257 having a recess in its forward end in which is carried the elastic platen block 1258 of rubber or other suitable 70 material.

The bushings 1250 hold the paper rollers out of frictional contact with the platen brackets. The bushings and the paper rollers and all the parts rotatable on the paper 75 roller shaft 1120 are caused to rotate with said shaft by means of frictional engagement with each other brought about by the clamping of the screw 1259 (Fig. 65) on said shaft.

Between each adjacent pair of paper rollers are the upper and lower inner paper shields 1260 and 1261 (Fig. 72), which form a continuation of the cylindrical surface of the paper rollers. These shields have angular extensions 1264, each extension having inwardly turned ears 1265 (Fig. 70) each provided with an opening receiving the bracket shaft 1252. The upper inner shield 1250 is pivotally supported on said rod by 90 said ears, being permitted to move pivotally because of the rounded upper face 1266 (Fig. 62) whereby access may be had to the screw 1256. This upper shield 1260 may be omitted if desired.

Partly surrounding or housing the lower inner shields 1261 and the lower part of the paper rollers 1248 are the outer paper shields 1267 provided with edge flanges 1268 on which are formed turned ears 1269 provided with openings receiving the bracket shafts 1129 (Figs. 66 and 71). These outer shields cooperate with the lower inner shields 1261 to form guides for the paper 100 1281 on which the tabulations are to be printed, the outer shields being continued upwardly in front of the paper rollers 1248, whereby are formed extensions 1284 (Fig. 67) between which the type of the type sectors pass when the paper is pressed against 105 them by means of the platen blocks 1258.

On the lower part of the flanges 1268 are formed small ears 1285 provided with perforations in which are carried release arm shafts 1286 (Figs. 67 and 71) on which are 115 pivotally carried the feed roller levers 1287 between the outer ends of which are journaled the paper feed rollers 1288, said roller engaging on opposite sides of the lower part of the paper rollers 1248 and passing thru 120 suitable openings in the lower shields 1267. These feed rollers are held in contact with the paper rollers by means of feed roller tension springs 1289 secured at opposite ends to the journaled pins 1290 of the rollers 125 (Figs. 67 and 71). The feed roller levers are held from accidental spreading away from the feed rollers by means of the springs 1289. The inner ends of the feed roller levers are provided with inwardly 130

pointing fingers 1292 engaging over the release rod 1294 guided in elongated slots 1295 in the end pieces 1117, (Fig. 66). When this release rod is raised the feed rollers 1288 are 5 moved to the position of the dotted lines of Fig. 71, out of contact with the paper rollers, for permitting the removal of the paper. This raising of the release rod is accomplished by means of release arms 1296 10 mounted on the release arm shaft 1297 carried in the end plates 1117 and actuated by the release lever 1298 (Fig. 65) adapted to be caught behind the shoulder 1299 of the inturned lug 1300 on the end plate 1117, to 15 hold the rollers in released position.

The paper feeding mechanism.

After each number is printed by the type of the type sectors, it is necessary to feed the 20 paper upwardly one or more spaces. This feeding is accomplished by means of engagement of the teeth of the feed ratchet 1301, mounted on the shaft 1120, by a two armed feed pawl 1302 (Fig. 66) pivotally 25 mounted on the feed pawl lever 1304 fulcrumed intermediately as on the stud shaft 1305 and driven by the link 1306, in turn driven by the drive lever 1307 mounted on the feed shaft 1308, said shaft being actuated 30 by the actuating arm 1309 fixed on said shaft and adapted to come into contact with and be moved by the abutment shaft 1310 carried on the abutment shaft bracket 1311 pivotally mounted on the tie plates 1102. 35 The brackets 1311 are limited in their rearward movement by the engagement, with the tie plates, of a shoulder 1312 formed by the lower edge of the lug 1314 laterally turned at the rear edge of said abutment shaft 40 brackets, and is yieldably held at its rearward limit of movement by a spring 1315 tensioned between said lug and a lug on the rear part of the shaft tie plate 1102.

When the carriage is moved forwardly 45 toward the type sectors the free end faces 1316 of the actuating arm 1309 engage and push down the abutment shaft 1310 against the action of the spring 1315 until said end face clears said shaft and permits the shaft 50 and its bracket to be snapped back by the spring 1315 until stopped by the shoulder 1312. Fig. 66 shows the abutment shaft the instant after it has cleared said end face.

After the printing has taken place and the 55 carriage moves rearwardly, the abutment shaft 1310 is engaged by the lower side of the actuating arm 1309 whereby said arm and drive lever 1307 are raised, thus rocking the pawl lever 1304 and lowering the 60 pawl 1302, thus turning the ratchet 1301 one or more teeth depending upon how soon the lower member 1317 of the pawl is permitted to engage the teeth. When it is desired that the ratchet feed only one tooth at a time, the 65 feed limiting lever 1318 pivotally mounted

on the upper part of the end plate 1117, is set in the position shown in Fig. 66, thus preventing the pawl member 1317 from continuing to engage the ratchet teeth after it has moved upwardly a distance of one tooth, 70 since the inclined inner face 1319 of said member will be engaged by the feed limiting pin 1320 mounted on the lower part of the feed limiting lever.

The feed limiting lever 1318 is somewhat 75 resilient and is provided with a pair of depressions 1321 either one of which is adapted to be engaged by a single projection on the inner face of the end plate 1117, depending upon whether the lever is shifted to the 80 right as shown in Fig. 66 or to the left. This arrangement serves to hold the lever in shifted position.

When it is desired that the pawl feed more than one tooth of the ratchet at a 85 time, the lever 1318 is shifted to the left of Fig. 66, thus moving the pin 1320 away from the lever pawl member 1317 permitting said member to be in engagement with the ratchet teeth during the downward movement of the pawl member for a distance of, for instance, two teeth. If desired, the parts may be so proportioned that three or more teeth may be fed at a time.

In order to prevent the feeding of the carriage more than the desired number of teeth, as when the machine is running at very high speed, the pawl 1302 is provided with an overthrow preventing cam 1322 adapted to engage between the teeth of the 95 ratchet against the inclined face thereof, whereby the ratchet is prevented from turning another tooth space after this pawl has ceased to travel in its feeding direction. A spring 1324 tensioned between the cam 1322 100 and the lever 1304 yieldably holds the pawl in engagement with the ratchet teeth. 105

The feeding mechanism is yieldably held in position to feed by means of a spring 1325 tensioned between the end plate 1117 110 and a perforated ear on the upper part of the inner end of the arm 1307.

In order to hold the ratchet wheel 1301 and the parts carried on the shaft 1120 in the positions in which they are fed by the 115 pawl, I provide a detent roller 1326 revolvably mounted on one end of the detent lever 1327 pivoted to the end plate 1117 and drawn by the spring 1328 strained between the other end of the detent lever and the 120 lower part of the end plate 1117, whereby said roller is yieldably pressed between the teeth of the ratchet and yieldably holds the ratchet in the position to which it is fed.

When it is desired to insert, remove or 125 feed the paper entirely independent of the feeding mechanism just described, I provide the mechanism shown in Figs. 67 and 71 comprising the paper feed gear 1329 (Fig. 71) fixed on the paper feed shaft 1120 130

and engaged by the idler gear 1330 rotatably mounted on the end plate 1117, the idler gear being in turn engaged by the knob gear 1331 fixed on the stud shaft 1105 rotatably 5 mounted in the end plate 1117 and carrying knurled knob 1332 (Fig. 67) by which said shaft and gears may be manually rotated.

While the paper is being fed and during the time of printing, it is desirable that it 10 be firmly held against the platens. This is accomplished by means of a clamping mechanism comprising a clamp bar 1333 (Fig. 66) carried between the outer ends of the clamp levers 1334 provided with intermediate longitudinal slots 1335 loosely receiving the paper feed shaft 1120 whereby the paper clamp bar is adapted to move toward and from the paper rollers as well as to revolve with said rollers. The inner ends of 15 the clamp levers are provided with small pins 1336 received in longitudinal slots 1337 in the lower ends of the spring levers 1338 intermediately fulcrumed on the end plates 1117 and drawn by a spring 1339 strained 20 between the upper end of the spring levers and the upper part of end plates 1117, whereby the clamp lever 1334 is yieldably drawn downwardly and the clamp bar 1333 yieldably presses against the paper and presses the paper against the paper rolls 1248.

This yieldable engagement maintains during the printing and feeding of the paper, but after feeding has taken place, as above 25 described, the releasing pin 1340 mounted on the cam bracket shaft 1341 comes into contact with the abutment shaft 1310 and forces the cam bracket shaft and the cam bracket 1342 to rock rearwardly whereupon 40 the cam edge 1343 forces outwardly the pin 1336 and therewith the lever 1334 and bar 1333 and also rocks said lever in a direction clockwise on Fig. 66, whereupon the bar 1333 is moved downwardly over the paper and later takes a fresh grip on the paper when the clamping lever is released by the cam on the next forward movement of the carriage and moves downwardly under the action of the spring 1336.

The inking mechanism.

While other methods of inking may be used, I prefer to use an inking ribbon of which the supporting and feeding means are indicated generally by reference numeral 1350 (Figs. 67 and 69); but as these form no part of the present invention, they are not further described.

The total signal mechanism.

When a total is printed it is desirable to show some visual signal to indicate that the number printed is a total. This is accomplished by shifting the carriage to the left when the total is printed whereby the total is

shown printed a little to the right of the alignment of the listed column.

Means for accomplishing this result will now be described.

As shown in Fig. 67, the lower edge of 70 the locating bar 1124 is provided with a notch 1380 in which engages the upper end of the vertical lever 1381 pivoted intermediate on the bracket 1382 fixed on the printing lever shaft 1139, the lower end of said 75 lever being pivotally connected to the intermediate part of the shift lever 783 (Fig. 65).

When the total head 797 engages in the groove 798 said head is shifted to the right, and the upper end of the lever 1381 is shifted 80 to the left whereupon the locating bar is moved to the left on the pin 1122 in the slot 1125, thus causing the printing to take place a slight distance to the right of the column.

Item non-printing total printing mechanism. 85

When by means of the lever 1160 (Fig. 1), the carriage has been set to a non-printing position so that the items accumulated are not printed, it is still desirable that the totals themselves be printed. In order to accomplish this printing automatically, there is provided the automatic printing lock lever 1387 (Fig. 67) pivotally mounted on the bracket 1388 fixed to the shaft 1139, the upper end of which lever engages in a notch 1390, the lower end engaging a transverse pin 1391 on the printing lock shaft 1150. When the carriage is shifted to the left, the bar 1124 is moved therewith, and carries the upper end of the lever 1387 to the left, whereupon the lower part of said lever, said printing lock shaft, and the cones 1145 are moved to the right thus locking together the upper and lower printing levers 1137 and 1138 and effecting the printing.

Operation of the printing carriage.

Paper is inserted in the rear opening between the outer shields 1267 and the inner lower paper shields 1261, and the paper rolls 110 1248 turned by means of the knob 1332 until the part on which it is desired first to print are opposite the platen blocks 1258. The feed limiting lever 1318 is set for the number of teeth it is desired that the feed ratchet 115 shall be fed. If desired the locking plate 1130 is unlocked and the carriage adjusted on the carriage rail and the carriage relocked.

The locking lever 1160 is set in locked or 120 unlocked position depending upon whether it is desired that the items be printed or not.

The machine is then started in operation as heretofore explained and the type is set 125 and the accumulators accumulate. If the locking lever is set in locked position the cams 1142 cause the printing levers and the carriage to reciprocate and the printing is effected.

When a total is taken the carriage is moved to the left just before the printing by means of the total signal lever 1381 engaging in the notch 1380 of the locating bar. If the locking lever 1260 has not been set to printing position, the automatic levers 1387 also cause the cones 1145 to lock the printing levers and print totals when the totals are set up and presented by the type

10 sectors.

I claim:—

1. In an apparatus of the character described, the combination of a card analyzer comprising settable pins; bar supports; rear 15 and intermediate receiving bars supported on said supports; adjustable push cables provided with inner wires and having the ends of their outer flexible casings secured to said receiving bars respectively, the rear ends of 20 said inner wires registering with said pins; an accounting machine controlled by said cables; and means for moving said bars backwardly for forcing said wires against said settable pins.

25 2. In an apparatus of the character described, the combination of an analyzer comprising analyzing members; an accounting machine having a total taking mechanism; shiftable means operated by the analyzing 30 members and adapted to shift the total taking mechanism after the analyzing members have been twice actuated by the shiftable means.

35 3. In an apparatus of the character described, the combination of an analyzer comprising settable pins; a latch plate for each row of settable pins adapted to be raised by said settable pins; a sensing lever operated by said latch plates; an accounting machine provided with a total taking mechanism; and a sensing mechanism operatively connected to the total taking mechanism and said sensing lever and adapted to operate the total taking mechanism.

40 4. In an apparatus of the character described, the combination of an analyzer comprising rows of settable pins provided at their upper edge with triangular projections forming vertical rear shoulders and forwardly inclined cam faces; a latch plate for 45 each row of settable pins and each provided with a shoulder adapted to be raised by said cam faces when the settable pins are moved forwardly; a sensing finger over each latch plate; a sensing lever operated by said sensing fingers whenever a sensing finger is rocked; an accounting machine provided with a total taking mechanism; and a sensing mechanism operatively connected to the

50 55 60 total taking mechanism and said sensing lever and adapted to operate the total taking mechanism whenever the sensing lever is operated twice.

5. In an apparatus of the character described, the combination of an analyzer com-

prising analyzing pins; vertical rows of settable pins in alinement with said analyzer pins respectively and provided at their upper edge with triangular projections forming vertical rear shoulders and forwardly inclined cam faces; a vertically movable latch plate for each vertical row of settable pins and each provided with shoulders adapted to be raised by said cam faces when the settable pins are moved forwardly; a rocking lever for each latch plate; a releasing finger pivoted to each rocking lever and adapted to engage under the latch plate when the rocking lever is rocked in one direction; a sensing finger pivoted to said rocking lever and adapted to engage over the latch plate when the rocking lever is rocked in the other direction; a reciprocatory releasing rod adapted to engage under said releasing finger; a sensing lever operated by said sensing fingers whenever a sensing finger is rocked; an accounting machine provided with a total taking mechanism; and a sensing mechanism operatively connected to the total taking mechanism and said sensing lever and adapted to operate the total taking mechanism whenever the sensing lever is operated twice.

6. In an apparatus of the character described, the combination of an analyzer comprising rows of settable pins; a latch plate for each of said rows and adapted to be raised by pins; a sensing lever adapted to be actuated by said latch plates; a slidable ratchet bar with ratchet teeth; a terminal block; a total taking cable secured in said terminal block and provided with terminal pins adapted to be engaged by said ratchet bar; a pawl pivoted to the sensing lever and adapted to engage said teeth; a detent adapted to prevent retrograde movement of the ratchet bar; a guide block mounted on the lower part of said supporting plate; a resetting slide vertically slidable on said guide block and adapted to engage under and release said pawl and detent from the ratchet bar; and an accounting machine having a total taking mechanism adapted to be shifted by said total taking cable for taking totals.

7. In an apparatus of the character described, the combination of an analyzer comprising rows of settable pins; feeding means for feeding cards to the analyzer; a ratchet bar provided with ratchet teeth; a lock releasing means adapted to be engaged by said bar; means actuated by the settable pins for moving said bar; and a locking means adapted to be released by said releasing means.

8. In an apparatus of the character described, the combination of an analyzer comprising vertical rows of settable pins each provided with a cam projection; feeding means for feeding cards to the analyzer; a latch plate for each of said rows and provided with shoulders adapted to be raised

- by said cam projections; a sensing lever adapted to be actuated by said latch plates; a supporting plate; a ratchet bar horizontally slidable on said supporting plate and 5 provided with ratchet teeth and a laterally turned lip; a terminal block secured on said supporting plate; and a total taking cable and a lock releasing cable secured in said terminal block and provided with terminal pins adapted to be engaged by said lip; a pawl pivoted to the sensing lever and adapted to engage said teeth; a detent mounted on said supporting plate and adapted to prevent retrograde movement of the ratchet 10 bar; a guide block mounted on the lower part of said supporting plate, and provided with vertically disposed lateral grooves; a resetting slide vertically slidable on said guide block and adapted to engage under 15 and release said pawl from the ratchet bar; an accounting machine having a total taking mechanism having a shift lever adapted to be shifted by said total taking cable for taking totals and a locking means adapted to 20 be released by said releasing cable for locking the feeding means.
9. In an apparatus of the character described, the combination of an analyzer comprising settable pins; an accounting machine 25 controlled by said settable pins; means for feeding cards to the analyzer and comprising a yieldable part; a sensing means actuated by the settable pins; a locking pawl actuated by said sensing means and provided with a locking shoulder adapted to lock said movable part.
10. In an apparatus of the character described, the combination of a frame; an analyzer comprising settable pins; feeding 30 means for the analyzer comprising bell-crank; a pair of reciprocatory side supports connected to said bell cranks; an accounting machine; connections adapted to control said accounting machine and supported between 35 said side supports and adapted to be forced thereby against the settable pins; a sensing means actuated by said settable pins for sensing card-designation changes; a locking pawl pivotally mounted on said frame and 40 actuated by said sensing means and provided with a locking shoulder adapted to lock said bell crank.
11. In an apparatus of the character described, the combination of a frame; a pair 45 of analyzer plates receiving cards therebetween; a reciprocatory pin box provided with analyzing pins adapted to pass through said plates; means for feeding cards to the analyzer plates comprising yieldable bell 50 cranks; settable pins in alinement with said analyzer pins; a pair of reciprocatory side supports connected to said bell cranks; an accounting machine; connections adapted to control said accounting machine and supported between said side supports and adapt- 55 ed to be forced thereby against the settable pins; a sensing means actuated by said settable pins for sensing card-designation changes; a locking pawl pivotally mounted on said frame and actuated by said sensing means and provided with a locking shoulder adapted to lock said bell crank. 70
12. In an apparatus of the character described, the combination of an analyzer; a feeding means therefor; an actuator therefor; and means operated by the analyzer for causing the actuating means to lock the feeding means. 75
13. In an apparatus of the character described, the combination of an analyzer; an analyzer feeding means; an analyzer actuating means; means for locking said feeding means; a sensing means operated by said analyzer; and means operated by the sensing means for causing said locking means to engage the actuating means for bringing about the locking of the feeding means. 80
14. In an apparatus of the character described, the combination of an analyzer; a feeding means for the analyzer comprising a movable part; means actuating said analyzer; a slidable bar; a latch pivotally mounted on said bar and adapted to engage and be moved by said actuating means; a sensing means actuated by said analyzer and adapted to cause said latch to engage said actuating means; and means actuated by said bar for locking said feeding means. 85
15. In an apparatus of the character described, the combination of a frame; an analyzer comprising settable pins; means for feeding cards to the analyzer and provided with a reciprocatory part having a laterally projecting part; an accounting machine controlled by said settable pins; means actuating said analyzer and comprising projections; a slidable bar provided with a cam face; a latch pivotally mounted on said slidable bar and adapted to engage behind said projections; a detent pivotally mounted on said frame and adapted to engage under said latch to hold it out of engagement with said projections; a sensing means actuated by said settable pins for sensing card designation changes and adapted to actuate said detent; and a locking pawl pivotally mounted on said frame and engaging said inclined face and provided with a locking shoulder adapted to engage and lock said lateral projection. 90
16. In an apparatus of the character described, the combination of a plurality of vertically movable pins; means for raising said pins; a vertically movable restoring plate associated with said pins and adapted to be raised when the pins are restored; rows of numeral stops in registration with said movable pins; a zero stop associated with each row of numeral stops and disposed over said restoring plate; and a con- 105
- 110
- 115
- 120
- 125
- 130

- nection between each zero stop and the associated row for depressing the associated row when the zero stop is raised by the restoring plate.
- 5 17. In an apparatus of the character described, the combination of rows of movable stops each provided with a pair of latching notches; shutter latches movably disposed between said rows and yieldably engaging in one of the notches for holding said stops raised; and means moving said stops out of said notches.
- 10 18. In an apparatus of the character described, the combination of rows of vertically movable numeral stops each provided with a pair of latching notches and a small projection between the notches; a zero stop associated with each row of numeral stops and provided with a pair of latching notches and a projection between the notches; shutter latches movably mounted between said rows and adapted to engage in either of said latching notches and to be engaged by said projections; means for raising the numeral stops; means for causing the zero stop to be lowered when a numeral stop is raised and the numeral stops to be lowered when a zero stop is raised; means for raising the zero stop; and a selecting means controlled by the stops.
- 15 19. In an apparatus of the character described, the combination of vertically movable pins; rows of numeral stops registering with said pins and each provided with a pair of latching notches in the sides thereof, a small projection between said notches, and long restoring notches in the lower part thereof; a zero stop associated with each row of numeral stops and provided with a pair of latching notches, a small projection between said notches, and a pin engaging recess; shutter supporting plates; shutter latches pivotally mounted between said shutter supporting plates and disposed between the rows of stops and engaging in either one of said latching notches of each of the stops; depressing levers disposed between said rows of stops, and provided with lateral projections engaging in said restoring notches; intermediately fulcrumed connecting levers loosely engaging the free end of said depressing levers and provided with a pin engaging in said recess of the zero stops; means for raising the zero stops; a rack bar disposed above each row of stops adapted to be stopped by said stop pins; analyzing means controlled said pins; and an accounting machine controlled by said rack bars.
- 20 20. In an apparatus of the character described, the combination of rows of vertically movable stops each provided with a pair of latching notches and a small projection between the notches; shutter latches movably disposed between the rows and yieldably engaging in one of the latches; means for operating the stops; and an accounting machine controlled by the stops.
- 25 21. In an apparatus of the character described, the combination of rows of vertically movable numeral stops each provided with a pair of latching notches in the side thereof, a small projection between said notches, and a long restoring notch in the lower part of the numeral stops; a zero stop associated with each row of numeral stops and provided with a pair of latching notches and a projection therebetween; shutter latches pivotally mounted between said rows of stops and engaging in one of the latching notches of each stop; depressing levers provided with lateral projections engaging in said restoring notches; connecting levers loosely engaging the free end of said depressing levers and engaging said zero stops; means for raising the numeral stops; and positioning means controlled by the stops.
- 30 22. In an apparatus of the character described, the combination of rows of movable numeral stops; a zero stop associated with each row of numeral stops; an operative connection between the zero stops and the associated numeral stops for causing the zero stop to be lowered when a numeral stop is raised and the numeral stops to be lowered when a zero stop is raised; means for raising the numeral stops; and a selecting means controlled by the stops.
- 35 23. In an apparatus of the character described, the combination of rows of movable numeral stops; a zero stop associated with each numeral stop; an operative connection between the zero stops and the associated numeral stops for causing the zero stop to be lowered when a numeral stop is raised and the numeral stops to be lowered when a zero stop is raised; means for raising the numeral stops; means for raising zero stops; and a selecting means controlled by the stops.
- 40 24. In an apparatus of the character described, the combination of rows of vertically movable numeral stops each provided in its lower part with a long restoring notch; a zero stop associated with each numeral stop and provided with a pin engaging recess; depressing levers at one end pivotally mounted between said rows of stops and provided with lateral projections engaging in said restoring notches; an intermediately fulcrumed connecting lever having one end loosely connected to the depressing levers and the other end provided with a lateral cam engaging in said pin receiving recess; means for raising numeral stops; means for raising the zero stops; and selecting means controlled by the stops.
- 45 25. In an apparatus of the character described, the combination of rows of numeral stops; a zero stop associated with each row

of numeral stops; shutter latches pivotally mounted between the rows of stops and engaging in either one of said latching notches of each of the stops; depressing levers disposed between said rows of stops, and engaging said numeral stops; connecting levers loosely engaging the free end of said depressing levers and connected to the zero stops; means for raising the zero stops; a rack bar disposed above each row of stops adapted to be stopped by said stop pins; analyzing means controlling said pins; and an accounting machine controlled by said rack bars.

26. In an apparatus of the character described, the combination of rows of movable stops; means for raising the stops; an actuating bar disposed above each row of stops and provided with an inwardly disposed shoulder; selecting means controlled by the bars; an abutment lever movably secured to each bar and provided with an outwardly disposed shoulder; a transverse reciprocating bar adapted to be disposed between said shoulders; and a device operatively connected to each actuating bar and the associated abutment lever and adapted to contact any raised stop and to lower and stop the associated abutment lever and to cause said inwardly disposed shoulder to clear said transverse bar.

27. In an apparatus of the character described, the combination of rows of vertically movable stops each provided with an inwardly and downwardly inclined upper face; means for raising said stop; a bar disposed above each row of stops and provided with an inwardly disposed shoulder; selecting means controlled by said bars; an upwardly spring pressed abutment lever fulcrumed to each bar and provided with an outwardly disposed shoulder adapted to be spaced from and opposed to said inwardly disposed shoulder; an elbow device pivotally mounted on each rack bar and loosely engaging the abutment lever and provided with a downwardly extending arm adapted to engage and remain behind any raised stop; and a transverse reciprocating bar adapted to be disposed between said shoulders.

28. In an apparatus of the character described, the combination of a pair of cheek plates; rows of numeral stops therebetween; means for actuating the stops; actuating members associated with each row of stops; selecting means controlled by actuating members; a drive bar having its end extending through the cheek plates; an abutment member secured to each actuating member in driving relation to said drive member and adapted to be moved out of said relation by any actuated stop; slide bars disposed outside of the cheek plates and secured to the ends of the drive bar respectively; spaced rollers on the cheek plates and guiding said

drive bars; and drive levers for reciprocating the slide bars.

29. In an apparatus of the character described, the combination of a pair of cheek plates provided with guiding slots; rows of movable stops disposed between said cheek plates; means for actuating the stops; actuating bars associated with each row of stops and provided with an inwardly disposed shoulder; an accounting machine controlled by the actuating bars; an abutment lever pivotally secured on each actuating bar and provided with an inwardly disposed shoulder and adapted to be lowered by any raised stop; a transverse drive bar disposed between said shoulders and projecting through said guiding slots; slide bars disposed outside of the cheek plates and secured to the ends of the drive bar respectively; spaced rollers mounted upon the outer face of the cheek plates and guiding said slide bars in horizontal position; drive levers intermediately fulcrumed upon said cheek plates and operatively connected to said slide bars; and cams for reciprocating said drive levers.

30. In an apparatus of the character described, the combination of an accumulator; means for actuating the accumulator and comprising a shiftable means for adapting the actuating means for accumulating or taking totals; a total shift lever engaging said shiftable means; a cam providing a cam groove terminating in a cam abutment; a plunger slidably mounted on said lever and adapted to be yieldably pressed into said groove; a pawl mounted on said lever and engaging said plunger to hold the same in retracted position; and a flexible connection secured to said lever and adapted to actuate said pawl for releasing the plunger.

31. In an apparatus of the character described, the combination of an accumulator; means for reciprocating the accumulator for taking totals or accumulating and comprising a shiftable means; a total shift lever engaging said shiftable means and provided with a supporting plate spaced therefrom; a plunger slidably mounted in said lever and plate and provided with a cam engaging plunger head on one end and a retaining head at the other end; a cam provided with a spiral peripheral cam groove adapted to receive said plunger head and terminating in a cam abutment; an elbow pawl mounted on said supporting plate and adapted to engage said head for holding the plunger retracted; a spring tending to hold said plunger into said groove; and a flexible connection comprising an inner wire and an outer casing, said outer casing being mounted on said plate and said inner wire engaging said elbow pawl; and means for operating said inner wire.

32. In an apparatus of the character de-

scribed, the combination of rows of stops each provided with a pair of lateral notches; shutter latches adapted to engage either one of said notches to each stop, and provided with end projections; an accounting machine controlled by said stops and comprising an accumulator adapted to accumulate or take totals; means for actuating said accumulator for accumulating or taking totals by two different actions; means for shifting said actuating means and comprising a cam provided with a shutter releasing cone; a shutter retracting plate slidably mounted on one of said supporting plates and provided with projections engaging between said end projections and with a cammed projection; and a shutter retracting lever engaging said cammed projection and engaged by said cone.

33. In an apparatus of the character described, the combination of upper and lower guide plates; rows of stops guided in said guide plates and each provided with a pair of lateral notches; supporting plates secured to said guide plates; shutter latches pivotally mounted between said supporting plates and adapted to engage either one of said notches of each stop, and provided with end projections; an accounting machine controlled by said stops and comprising an accumulator adapted to accumulate or take totals; means for actuating said accumulator for accumulating or taking totals by two different actions; means for shifting said actuating means and comprising a cam provided with a shutter releasing cone; a shutter retracting plate slidably mounted on one of said supporting plates and provided with projections engaging between said end projections and with a cammed projection; and a shutter retracting lever engaging said cammed projection and engaged by said cone.

34. In an apparatus of the character described, the combination of an adding mechanism comprising actuating members and a drive member; an abutment carried on each actuated member and adapted to be yieldably pressed into driving engagement with said drive member; and a plurality of column cut out bars adapted to be moved into position to engage and hold said abutments out of engagement with the drive member.

35. In an apparatus of the character described, the combination of an adding mechanism comprising actuating bars; an abutment lever pivoted to each actuating bar and provided with a rear extension; a transverse drive bar; means for pressing said abutment levers upwardly into driving engagement with said drive bar; an accumulating mechanism operatively connected to said actuating bars; upper and lower comb plates; column cut-out slide bars slidably received in said

comb plate and adapted to hold said abutment levers depressed and provided with a pair of shoulders adapted to engage above and below one of said comb plates; and means for yieldably holding said shoulders into engagement with said comb plate.

36. In an apparatus of the character described, the combination of a pair of cheek plates; an adding mechanism therebetween comprising type sectors and rack bars co-operating with the type sectors and each 75 an inwardly turned shoulder; an abutment lever pivoted to each rack bar and provided with an outwardly disposed shoulder and with a rear extension; a transverse drive bar adapted to be disposed between said 80 shoulders for reciprocating the rack bars; an accumulating mechanism associated with said type sectors; a locking comb plate disposed between the outer ends of said cheek plates; a guiding comb plate beneath the 85 locking comb plate; column cut out slide bars slidably received in said comb plates and provided at its upper part with a pair of shoulders adapted to engage above or below said locking comb plate, and at its 90 lower end with a laterally turned lip adapted to engage against and adapted to hold said abutment levers depressed; a spring for holding said cut-out bars in locking engagement with said locking comb plate; and 95 retaining rods adapted to retain said cut-out bars in said guiding comb plates.

37. In an apparatus of the character described, the combination of a pair of cheek plates; an adding mechanism therebetween 100 comprising a reciprocating accumulator carriage comprising a shaft projecting through the cheek plates; yieldable actuating lever secured to said shaft for reciprocating said carriage; and a manually operable accumulator cut-out lever intermediately fulcrumed to the outer face of one of the cheek plates and having a hooked inner end adapted to engage over the ends of the accumulator shaft and to hold the same out of operation.

38. In an apparatus of the character described, the combination of an adding mechanism comprising a reciprocating accumulator and shifting means for shifting the 115 accumulator into total taking relation; an anchor means; means adapted to shift the anchor means into holding engagement with the accumulator after the accumulator has accumulated once whereby the accumulator is held out of action; and means adapted to release said anchor means when said shifting means is shifted, whereby a total is printed of the one accumulation that was transferred to the accumulator.

39. In an apparatus of the character described, the combination of an adding mechanism comprising a reciprocating accu-

lator and means for shifting the accumulator into total taking relation; an anchor lever adapted to hold said accumulator against reciprocation; a retracting lever 5 yieldably connected to the anchor lever; means engaging said retracting lever for moving the anchor lever into holding relation with the accumulator; a latch operatively connected to said shifting means for holding said retracting lever in position to hold the anchor lever in holding relation with the accumulator, said latch adapted to be released by said shifting lever; and means for moving the anchor lever out of holding 10 relation when the shifting lever is thus released.

40. In an apparatus of the character described, the combination of an adding mechanism comprising a reciprocating accumulator carriage; an anchor lever adapted to hold said carriage from reciprocation; a retracting lever adapted to move said anchor lever into holding relation with the carriage; a reciprocating member; an actuating bar pivotally connected to said retracting lever and adapted to be engaged by said reciprocating member for causing said retracting lever to move the anchor lever into holding relation; a latch for holding said 25 retracting lever in said holding position; a shiftable means for moving said accumulator to total taking position; a connection between said shiftable means and said latch for causing said latch to release said retracting lever; and yielding means for causing said anchor lever to release the carriage when said latch releases the retracting lever.

41. In an apparatus of the character described, the combination of an analyzer comprising settable members; a machine comprising actuatable devices; connections between said devices and members; and means for causing relative movement between said 40 connections and said members while said members are stationary for actuating said devices.

42. In an apparatus of the character described, the combination of an analyzer comprising settable members; an accounting machine comprising actuatable devices; connections between said devices and members; and means for moving said connections relative to said members for actuating said stops.

43. In an apparatus of the character described, the combination of a card analyzer comprising settable members; an accounting machine comprising stops; connections between said stops and members; and means for causing relative movement between said 50 connections and said members while said members are set stationary for actuating said stops.

44. In an apparatus of the character de-

scribed, the combination of an analyzer element; and an accounting machine provided with a total taking and registering mechanism either of which may be operatively connected to any of said elements.

45. In an apparatus of the character described, the combination of an analyzer comprising settable members; latches for the settable members and adapted to be moved by the members; an accounting machine provided with a total taking mechanism having operative connection with said latches, and with a registering mechanism.

46. In an apparatus of the character described, the combination of an analyzer comprising settable members; latches for positively locking the settable members set and adapted to be moved by the members; and an accounting machine provided with a total taking mechanism operatively connected to said latches for shifting the total taking mechanism when the latches are operated.

47. In an apparatus of the character described, the combination of an analyzer comprising settable pins; latch plates for positively locking the settable pins adapted to be moved by the pins; an accounting machine provided with a total taking mechanism; and a sensing mechanism operatively connected to the total taking mechanism and said latches for shifting the total taking mechanism when the latches are operated.

48. In an apparatus of the character described, the combination of an analyzer comprising analyzer members; a movable member adapted to be moved an increment each time an analyzer member is actuated the first time; and an accounting machine having a total taking mechanism adapted to be shifted by the second increment of movement of said movable member.

49. In an apparatus of the character described, the combination of an analyzer comprising analyzer members; a movable member adapted to be moved an increment each time an analyzer member is actuated the first time; means for restoring the movable member; and an accounting machine having a total taking mechanism adapted to be set in operation by the second increment of movement of said movable member.

50. In an apparatus of the character described, the combination of an analyzer comprising settable members; a latch for, and actuated by, the members; a ratchet member moved increments by the latch; means for restoring the ratchet member; and an accounting machine having a total taking mechanism adapted to be shifted by said ratchet member for taking totals.

51. In an apparatus of the character described, the combination of an analyzer comprising rows of settable pins; a latch plate

- for each of said rows and adapted to be actuated by the pins; a ratchet bar provided with ratchet teeth; means actuated by the latch plate and adapted to engage said teeth; 5 means adapted to prevent retrograde movement of the bar; a means adapted to release the preventing means; and an accounting machine having a total taking mechanism adapted to be shifted by said ratchet bar for taking totals.
52. In an apparatus of the character described, the combination of an analyzer; feeding means for feeding cards to the analyzer; and a locking means for locking 15 the feeding means.
53. In an apparatus of the character described, the combination of an analyzer; feeding means for feeding control-means to the analyzer; and a locking means adapted 20 to be actuated by said analyzer for locking the feeding means.
54. In an apparatus of the character described, the combination of an analyzer comprising settable members; feeding means for 25 feeding cards to the analyzer; a movable member; means actuated by the settable members for moving said movable member; and a locking means adapted to be released by said movable member for locking the 30 feeding means.
55. In an apparatus of the character described, the combination of an analyzer; yieldably actuated means for feeding cards to the analyzer; and a locking means adapted 35 to lock said feeding means.
56. In an apparatus of the character described, the combination of an analyzer; a yieldably actuated means for feeding cards to the analyzer; and a locking means actuated 40 by the said analyzer and with a locking shoulder adapted to lock said feeding means.
57. In an apparatus of the character described, the combination of an analyzer; an accounting machine controlled by said analyzer; means for feeding control-means to the analyzer and comprising a yieldable part; and a locking pawl actuated by the said analyzer and adapted to lock said yieldable 45 part.
58. In an apparatus of the character described, the combination of an analyzer comprising settable pins and a pin box; a card feeding means therefor; an actuator for the pin box; and means operated by the analyzer for causing the actuating means to lock the feeding means.
59. In an apparatus of the character described, the combination of an analyzer; a total taking pin in said analyzer; a connection; a 50 slideable plunger adapted to be, by said pin, opposed to said connection; means adapted to push the plunger to actuate said connection; and an accounting machine provided with a total taking mechanism adapt- ed to be brought into operation by said connection.
60. In an apparatus of the character described, the combination of an analyzer; a forwardly pressed total taking pin adapted to be projected through said analyzer; a plunger support adapted to be lowered by said total taking pin when thus projected; a flexible push cable having its outer casing secured in said terminal block and its inner wire terminating in a terminal pin near said plunger support; a plunger on said support and adapted to oppose the terminal pin when the support is lowered; means adapted to push the plunger against the terminal pin; and an accounting machine provided with a total taking mechanism adapted to be brought into operation by said flexible cable.
61. In an apparatus of the character described, the combination of an analyzer adapted to receive cards therein; a forwardly pressed total taking pin adapted to be projected through said analyzer when a total card is therein; a total taking lever adapted to be rocked by said total taking pin when thus projected; a plunger support pending from said total taking lever; a terminal block; a flexible push cable having its outer casing secured in said terminal block and its inner wire terminating in a terminal pin near said plunger support; a plunger slideable in said plunger support and adapted to be opposed to the terminal pin when the total lever is actuated; means adapted to push the plunger against the terminal pin when thus opposed; and an accounting machine provided with a total taking mechanism adapted to be brought into operation by said flexible cable.
62. In an apparatus of the character described, the combination of actuating pins; a restoring plate; numeral stops in registration with the pins; zero stops adapted to be raised by the restoring plate; means for lowering the pins and raising the restoring plate; means for restoring the numeral stops; and an accounting machine controlled by said stops.
63. In an apparatus of the character described, the combination of movable pins; means for raising the pins; a restoring plate associated with the pins; numeral stops in registration with the pins; zero stops in registration with the restoring plate; means for lowering the pins and raising the restoring plate; a connection between the zero stops and the numeral stops for lowering the numeral stops as the zero stops are raised; and an accounting machine controlled by said stops.
64. In an apparatus of the character described, the combination of rows of movable stops; means for actuating the stops; actuating members associated with each row of

stops; selecting means controlled by the actuating members; a drive member; an abutment member movably secured to each actuating member in driving relation to said drive member; a device operatively connected to each actuating member and associated with the abutment member and adapted itself to engage an actuated stop, thereby to stop the actuating member and throw the abutment member out of driven relation with the drive member; and separate means for preventing retrograde movement of the actuating member.

65. In an apparatus of the character described, the combination of a total-taking mechanism comprising a shiftable actuating part; connections both adapted to bring about the actuation of said part; and an analyzer having a total card sensing means both adapted to operate said connections.

66. In an apparatus of the character described, the combination of a total-taking mechanism comprising a shiftable actuating part; a cam; a device movably mounted on said part and adapted to engage said cam to actuate said part; a pair of flexible connections each having its outer casing secured to said part and its inner wire adapted to bring about the actuation of said device; and an analyzer change sensing means adapted to operate said flexible connections respectively.

67. In an apparatus of the character described, the combination of a total-taking mechanism comprising a shiftable part; a cam providing a cam groove; a plunger slidably mounted on said part and adapted to engage said groove; a flexible connection having its active end secured to said part for actuating said plunger; and means adapted to operate said flexible connection.

68. In an apparatus of the character described, the combination of an accumulator; means for actuating the accumulator and comprising a shiftable means for adapting the actuating means for accumulating or taking totals; a total shift lever engaging said shiftable means; a cam providing a cam groove terminating in a cam abutment; a plunger slidably mounted on said lever and adapted to be yieldably pressed into said groove; a pawl mounted on said lever and engaging said plunger to hold the same in retracted position; a block on said lever; a pair of flexible connections each having its outer casing secured to said block and its inner wire adapted to engage and release said pawl from said retaining hand; and an analyzer having a total card sensing means and a designation change sensing means adapted to operate said flexible connection respectively.

69. In an apparatus of the character de-

scribed, the combination of an adding mechanism comprising driven actuating members; and a plurality of column cut-out members adapted to be moved into position to engage and hold said actuating member out of operative position.

70

70. In an apparatus of the character described, the combination of an adding mechanism comprising a drive member and abutment members adapted to be yieldably pressed into driving engagement with said drive member; and cut-out members adapted to be moved into position to engage and hold said abutment members out of engagement with the drive member.

71. In combination, a reciprocator accumulator; a lever having a yieldable active arm connected to said accumulator; means for reciprocating the motive part of the lever; and means for at will limiting movement of the outer end of the active arm while the motive part still operates, for disabling the accumulator.

72. In combination, a plurality of actuating members; a reciprocator accumulator; a lever having an active arm comprising an inner fulcrumed-link and an outer link operatively connected to said accumulator; means for reciprocating the fulcrumed-link; a yieldable spring means connecting said links for yieldably moving said outer link and the accumulator towards the actuating members as the fulcrumed-link is actuated; and means for limiting movement of the outer link, relative to the fulcrumed-link, under the action of the spring means.

100

73. In an apparatus of the character described, the combination of rows of movable stops; a reciprocator actuating bar above each row; an abutment lever pivoted to each rack bar and provided with a rearwardly disposed shoulder; a reciprocating drive bar adapted to engage said shoulders when the levers are raised; a device on each reciprocator bar and connected to each lever and adapted to engage any raised pin and thereby lower the lever as the drive bar moves forward; a depressing rod disposed just above said abutment levers; and means connected to the rod for depressing the rod and the levers.

105

74. In an apparatus of the character described, the combination of settable stops; a reciprocator bar; an abutment lever pivoted to each bar; a drive bar adapted to engage said levers when raised; devices adapted to engage any set stop and thereby lower the lever from the drive bar; a depressing rod disposed just above said abutment levers; a link pending from each end of said rod; intermediately fulcrumed intermediate levers having their active ends connected to the lower ends of said links; a pair of cam levers each provided with a cam

125

engaging roller and operatively connected to the intermediate lever; and cam wheels each provided with a groove receiving said roller.

5 75. In an apparatus of the character described, the combination of rows of vertically movable stops; a reciprocatory actuating bar; a pawl on each bar; an abutment lever pivoted to each bar; a spring disposed between said pawl and abutment lever, whereby the lever and pawl are raised; a drive bar adapted to engage said levers when the levers are raised; devices adapted to engage any raised stop and thereby lower the lever from the drive bar; a ratchet plate adapted to be engaged by said pawls; a pair of intermediately fulcrumed lifting levers having their active arms operatively connected to opposite ends of the plate; a depressing rod connecting the motive ends of said lifting levers and disposed just above said abutment levers; and means connected to the rod for simultaneously depressing the rod and thereby 25 raising said ratchet plate.

76. In an apparatus of the character described, the combination of movable stops; reciprocatory bars; a pawl on each bar; an abutment lever pivoted to each rack bar; a drive bar adapted to engage said levers when raised; devices adapted to engage any set stop and thereby lower the levers from the drive bar; a vertically movable horizontally disposed ratchet plate disposed above said pawls and provided with transverse ratchet ribs; a pair of intermediately fulcrumed lifting levers having their active arms operatively connected to opposite ends of the plate; a depressing rod connecting the active ends of said lifting levers and disposed just above said levers; a link pending from each end of said rod; intermediately fulcrumed intermediate levers having their active ends connected to the lower ends 45 of said links; a pair of cam levers each provided with a cam engaging roller and operatively connected to the intermediate lever; and cam wheels each provided with a groove receiving said roller and so shaped that said 50 ratchet plate is raised out of contact with the holding pawls while the rack bars are being retracted.

77. In an apparatus of the character described, the combination of a registering mechanism comprising settable members; an accounting machine comprising a plurality of stops; connections between said stops and said settable pins; and means for moving said connections against said settable pins, for actuating said stops while the settable pins are stationary.

78. In an apparatus of the character described, the combination of a plurality of

settable members; means for setting the settable members; an accounting machine comprising a plurality of stops; connections between said stops and said settable members; and means for forcing said connections back against said settable pins, for actuating said stops while the settable pins are stationary. 70

79. In an apparatus of the character described, the combination of a card analyzer comprising settable pins; means for setting the settable pins; an accounting machine comprising a plurality of stops; flexible 75 connections between said stops and said settable pins; and means for forcing said connections back against said settable pins, for actuating said stops while the settable pins are stationary. 80

80. In an apparatus of the character described, the combination of analyzer elements; and an accounting machine provided with a total taking and a registering mechanism both operatively connected to 85 certain of said elements.

81. In an apparatus of the character described, the combination of analyzer elements; and an accounting machine provided with a total taking mechanism operatively 90 connected with some of said elements, and a registering mechanism operatively connected to all of said elements.

82. In an apparatus of the character described, the combination of analyzer elements; an accounting machine provided with a total taking and a registering mechanism; and means whereby said total taking mechanism may be at will operatively associated with any of said elements. 95 100

83. In an apparatus of the character described, the combination of an analyzer having rows of analyzer elements; an accounting machine provided with a total taking and a registering mechanism both operatively connected to any of said rows of elements; and means whereby said total taking mechanism may be at will discounted from 105 said rows.

84. In an apparatus of the character described, the combination of a total taking mechanism comprising a shiftable actuating part; a movable driven member; a device movably mounted and entirely carried on said part and adapted when moved into 110 engagement with the drive member to bring about the actuation of said part thereby to set in operation the total taking mechanism; and a flexible connection secured to said shiftable part and adapted to bring 120 about movement and engagement of said device.

85. In an apparatus of the character described, the combination of a total taking mechanism comprising a shiftable actuating part; a rotary cam member; a device 125

movably mounted and entirely carried on said part and adapted when moved into engagement with the cam member to bring about the actuation of said part thereby to set in operation the total taking mechanism; and a flexible connection secured to said shiftable part and adapted to bring about movement and engagement of said device.
